[57] ABSTRACT

Fluidic techniques and elements are disclosed for performing various irrigation functions, including sequential filling of irrigation ditches by automatic operation of fluidic diverter elements. A novel diverter element is disclosed which is operable either as a switching or proportional type fluidic amplifier, and includes a weir formed at the downstream end of its output passages and a vortex chamber projecting outwardly from its interaction region for converting part of the power stream flow to vortical flow which augments aspiration of ambient control fluid. In a further aspect of the invention, hard cut-off of liquid flow is achieved with a roller curtain gate comprising a flexible sheet adapted to be selectively rolled or unrolled over a flow opening. Also disclosed is a fluidic control for a siphon whereby venturi action in a fluidic element is employed to create a suction force which initiates siphon flow. A number of fluidic level sensing schemes are disclosed for controlling sequential irrigation ditch filling, and fluidic techniques are disclosed which compensate for environmental factors in the level detection schemes.

FLUIDIC IRRIGATION

BACKGROUND OF THE INVENTION

The present invention relates to fluidics technology, and in particular to fluidic techniques utilized in controlling irrigation systems.

The need for automation in irrigation is becoming acute in many of the nation's large agriculture areas where natural rainfall must be greatly augmented with irrigation water. The need arises primarily from the increasing costs and shortage of manual labor which has been traditionally used to operate irrigation systems. In limited areas, this problem is being attacked by the automation of sprinkler irrigation systems; however, these require the combination of available electricity at a high power level to operate pumping facilities. The pumps and associated plumbing of sprinkler systems also represent a large capital investment, which is currently economically unfeasible in most of the irrigated farm areas. The automation of surface irrigation systems therefore is currently lacking badly for want of a practical low cost technical approach. The automatic irrigation techniques, primarily fluidic techniques, described herein have been well received in the industry and represent a very promising approach to the solution of an eminently serious agricultural problem.

It is therefore a primary object of the present invention to provide techniques for use in automating irrigation control systems.

It is another object of the present invention to employ fluidic techniques for providing relatively inexpensive automatic control capabilities in irrigation control systems.

The overall system concept described herein employs fluidic diverter elements operable in various sequences and combinations of sequences to distribute water as required among a plurality of irrigation ditches. In implementing the system it was necessary to develop novel fluidic diverter elements, novel liquid level detection and control techniques, novel flow shut-off devices, and novel techniques for adapting the irrigation system to changes in the localized environment. These various elements and techniques, as well as the overall system concept, all form a part of the present invention. For example, assume that eight irrigation ditches are to be filled in sequence so that when one ditch fills up flow is to be switched to the second, etc. This can be accomplished automatically by using a series of bistable fluidic diverters and associated liquid level sensors arranged to sequentially switch the diverters accordingly as each ditch is filled. It was found that conventional fluidic bistable elements were not able to divert large mass flows of water nor were they able to respond accurately to conventional liquid level detection and flow control techniques. Consequently novel diverter elements and associated level detection and flow control techniques were conceptualized for particular utilization in irrigation control systems, although these elements and techniques have a somewhat broader application apart from irrigation systems.

It is therefore another object of the present invention to provide a novel fluidic diverter element for particular utilization in irrigation control systems.

It is another object of the present invention to provide novel flow control techniques for facilitating the regulation and shut-off of large mass liquid flows, as required in irrigation systems.

It is still another object of the present invention to provide liquid level detection and control techniques having particular utilization in irrigation control systems.

SUMMARY OF THE PRESENT INVENTION

In accordance with one aspect of the present invention a novel fluidic diverter element of the wall attachment type selectively diverts large mass flows of water at relatively low dynamic pressures. The diverter has relatively wide outlet passages as compared to those of conventional fluidic diverter devices, and has weir structures formed at the downstream ends of its outlet passages. The weirs prevent water in the non-

flowing outlet passage from spilling over into the irrigation ditch fed by that output passage. The switching control in the element is accomplished by controlled aspiration of ambient air through a control port. Aspiration is augmented by a vortex chamber arranged to peel off a portion of the power stream, creating vortical flow therefrom which produces a relatively large suction force at the control port. The augmented suction permits utilization of long lengths of control lines without intolerable control signal losses.

10 The above described diverter element can be designed for analog or proportional operation by enlarging the control port cross-section to permit sufficiently high rates of induction of ambient air to prevent attachment of the water power stream to the diverter sidewalls. The control ports may comprise fittings of different sizes so that a single diverter element can be used for either switching or proportional operation by proper choice of fittings.

The diverter control ports may communicate with liquid level detection devices which can be either bistable or analog 20 as required. In accordance with one aspect of the present invention, a novel analog liquid level sensor employs an inverter cup having a slotted sidewall through which fluid is aspirated by a diverter control port. As the level of the liquid rises in the inverted cup, the slotted cup presents a gradually increasing 25 flow restriction for aspirated ambient air flow to the control port. The resulting decrease in aspirated air flow produces concomitant changes in the diverter power stream position, and if the diverter is of the proportional type the diverter output pressure comprises a measure of the liquid level being sensed.

In order to provide hard cut-off of liquid flow in an irrigation system, the present invention provides a novel roller curtain gate and associated control apparatus. The gate comprises a flexible sheet of sufficient size to block liquid outflow 35 through an aperture in a reservoir wall when the sheet is placed over that aperture. The flexible sheet has one edge secured to the wall adjacent the aperture and is adapted to be rolled and unrolled over the aperture in response to predetermined system conditions, such as level detection, turn on, etc.

A novel control arrangement for the roller curtain comprises a leaky bucket, pivotable under the weight of water to roll the curtain. The leaky bucket is fed by an outlet leg of a diverter and empties through drain holes when the diverter 45 switches away from the bucket. The diverter is controlled, for example, by a liquid level detector so that reservoir outflow is provided as needed.

In accordance with a further aspect of the present invention, a fluidic control device is provided to initiate and terminate flow through a siphon. Siphons are presently in widespread use to transfer water from supply ditches to growing areas in irrigation systems. The present invention utilizes venturi suction from an outlet passage of a fluidic diverter element. When flow in the diverter element is through that outlet 50 passage, venturi action sucks air from the top of the siphon neck, initiating water flow through the siphon. When flow in the diverter is switched to the other outlet passage, ambient air enters the siphon via the venturi section to cut-off siphon flow. The siphon may be rotated to provide different heights of the siphon neck.

Where hard or total shut-off capability is not required, a continuous flow type liquid level control may be employed. This comprises a vortex element controlled by a diverter element which in turn is controlled in accordance with the level of liquid. One leg of the diverter supplies flow tangentially to the vortex element to controllably induce vortical flow therein. The flow through the vortex element is radial in the absence of tangential diverter flow, the radial flow experiencing minimum impedance and hence providing maximum outflow. Increased tangential flow from the diverter induces commensurate vorticity in the flow through the vortex element, and the greater the vorticity the smaller the outflow.

A number of modified liquid level detection techniques are disclosed. In one such technique an inverted cup type level de-

tector is placed near the upstream end of an irrigation ditch and provides an indication of the liquid level at the downstream end. This is accomplished by using the inverter cup to sense the level in a container into which liquid ingress is restricted so that the liquid level in the container rises slowly, in close approximation to the liquid level rise at the downstream end of the ditch.

Another disclosed liquid level detector is employed in an irrigation ditch and controls the frequency of filling the ditch with water. This is accomplished by employing an inverter cup in conjunction with a basin and permitting the basin to fill with liquid to a predetermined level above the level-sensing mouth of the cup shutting off the ditch supply. The evaporation rate of liquid in the basin controls the time required for the basin liquid level to fall below the cup sensing mouth and re-initiate inflow of liquid to the ditch.

A rainfall override may be provided with a liquid level detector to prevent unnecessary filling of irrigation ditches where rainfall has supplemented irrigation requirements. The rainfall override comprises a rain-collecting funnel arrangement disposed to add rain water to the basin associated with a liquid level sensing inverted cup. The amount of rain water so added is calibrated in accordance with the amount of rainfall, and filling of the ditch is delayed accordingly.

Other override devices, responsive to soil moisture content, ambient temperature, and ambient wind are disclosed in interlocking relationship with a fluidic diverter for preventing or initiating irrigation flow in accordance with these ambient conditions.

These and other fluidic elements and circuits are employed in irrigation systems which are automatically controlled as required to service one or more individual parcels of land.

BRIEF DESCRIPTION OF THE DRAWINGS

The above and still further objects, features and advantages of the present invention will become apparent upon consideration of the following detailed description of the various specific embodiments thereof, especially when taken in conjunction with the accompanying drawings, wherein:

FIG. 1 is a view in perspective of a bistable diverter valve employed in the irrigation control systems of the present invention;

FIG. 1a is a side view of the diverter of FIG. 1;

FIG. 2 is a view in perspective of a proportional type of fluidic diverter valve employed in the irrigation control systems of the present invention;

FIG. 3 is a front view in perspective of a roller curtain gate and control apparatus capable of cutting-off liquid flow in an irrigation system;

FIG. 4 is a rear view in perspective of the roller curtain gate of FIG. 3;

FIG. 5 is a view in section illustrating the mounting of the roller curtain gate of FIGS. 3 and 4;

FIG. 6 is a diagrammatic illustration of a roller curtain control apparatus of the type illustrated in FIGS. 3 and 4 employed as an upstream liquid level control device;

FIG. 7 is a diagrammatic illustration of a roller curtain control apparatus of the type illustrated in FIGS. 3 and 4 employed as a downstream liquid level control device;

FIG. 8 is a diagrammatic illustration of a continuous flow type liquid level control arrangement suitable for use in the irrigation systems of the present invention;

FIG. 9 is a view in perspective of a fluidically controlled siphon constructed in accordance with the principles of the present invention;

FIG. 10 is a view in perspective of a modification of the embodiment of FIG. 9 wherein the siphon is adjustable in

FIG. 11 is a view in perspective of another embodiment of the fluidically controlled siphon of the present invention;

FIG. 12 is a diagrammatic illustration of a fluidic analog liquid level control apparatus;

FIGS. 13, 14 and 15 are diagrammatic illustrations of respective liquid level sensor devices constructed in accordance with the principles of the present invention;

FIG. 16 is a diagrammatic illustration of a liquid level sensor incorporating a rainfall override arrangement;

FIG. 17 is a schematic illustration of a two-stage fluidic diverter for irrigation applications and employing a novel fluidic interstage switching arrangement;

FIG. 18 is a diagrammatic illustration of a bistable fluidic diverter element for use in an irrigation system wherein the quantity of diverted liquid determines the switching time of the diverter element;

FIG. 19 is a schematic illustration of a fluidic irrigation diverter used in conjunction with a soil moisture detector for controlling diverter operation;

FIG. 20 is a schematic illustration of a fluidic irrigation diverter employed in conjunction with a temperature sensing element for controlling diverter operation;

FIGS. 21 and 22 are respective diagrammatic illustrations of respective wind monitoring devices for utilization in controlling irrigation diverter operation;

FIG. 23 is a schematic illustration of a fluidic flow balancing system for use in an irrigation control system;

FIG. 24 is a schematic illustration of a multiple flow balancing system employing the principals of the embodiment illustrated in FIG. 23;

FIGS. 25 and 26 are schematic illustrations of respective fluidic diverter circuits employed in an irrigation system in which diverter switching is delayed for a predetermined period of time after a detected liquid level reaches a predetermined level;

FIG. 27 is a schematic illustration of a fluidic automatic irrigation system for use in a high sloping terrain environment;

FIG. 28 is a schematic illustration of a self-cycling multiple-ditch irrigation network;

FIG. 29 is a diagrammatic illustration of an irrigation scheme in which a plurality of fluidic diverters are serially arranged; and

FIGS. 30 and 31 are respective diagrammatic and schematic illustrations of a fluidic irrigation system in a relatively low slope terrain wherein fluidically controlled siphons are employed to conduct liquid from supply ditches to the area to be irrigated.

DETAILED DESCRIPTION OF THE PREFERRED EMBODIMENTS

Referring now to FIGS. 1 and 1a of the accompanying drawings, there is illustrated a bistable fluidic diverter element 10 specifically arranged to divert water or liquid flow having a relatively low pressure head. Diverter element 10 may be constructed of any suitable plastic or metal material which is molded or otherwise formed to provide the various passages and channels described below. It is contemplated, though certainly not mandatory, that the element be formed by joining a top plate 11 to the edges of upstanding sidewalls 13 and 15 of a bottom plate, the plates being joined in fluid-tight relationship. A generally rectangular inlet opening 17 is adapted to receive pressurized liquid and conduct same to a narrow throat or power nozzle 19 having a downstream end which opens into an interaction region or chamber 20. The flow restriction provided by power nozzle 19 is achieved by the convergence of sidewalls 13 and 15 in a downstream direction from inlet 17. In interaction chamber 20, immediately downstream of power nozzle 19, the sidewalls 13 and 15 are provided with opposed and generally semi-circular configured projections 21 and 23 extending outwardly of element 10. Control ports 25 and 27 communicate through top plate 11 with respective projections 21 and 23. For the particular configuration illustrated in FIG. 1, it is to be noted that control port 25 is of significantly larger cross section than control port 27. The effect of this is described in detail below.

Immediately downstream of projections 21 and 23 respective sidewalls 13 and 15 diverge in a downstream direction at a sufficiently gradual angle to permit a water power stream to attach to either sidewall when the pressure between the power stream and the sidewall falls somewhat below ambient. This wall attachment phenomenon is well known in the fluidics art and is sometimes referred to as Coanda effect. A flow divider 29 is interposed between sidewalls 13 and 15, somewhat downstream of the projections 21 and 23, forming respective outlet passages 31 and 33. At the downstream ends of outlet passages 31 and 33 the bottom plate of diverter element 10 slopes upwardly toward top plate 11 to form respective weirs 35 and 37. The important characteristic of weirs 35 and 37 is that when diverter element 10 is placed flat on its bottom plate the uppermost portion of weirs 35 and 37 extend to the height of or slightly above the edge of top plate 11 which defines inlet opening 17. Consequently, when water flows from outlet passage 33, weir 35 prevents water in outlet passage 31 from spilling out of element 10. In effect then the weirs 35 and 37 prevent outflow of water from their respective outlet passages in the absence of a predetermined pressure or head in that outlet passage. The height of the weirs is best illustrated in FIG. 1a.

In operation, water entering the inlet opening 17 is diverted into either of the two outlet passages 31 and 33 and exits over a respective one of weirs 35 and 37. The fundamental operating principle of element 10 is based on wall attachment, otherwise known as the Coanda effect, where a submerged stream of fluid tends to attach itself to a closely proximate wall, in this case either of sidewalls 13 and 15. Depending upon which side of the power stream experiences a more negative pressure, the power stream attaches to that sidewall and flows out through the appropriate outlet passage. The projections 21 and 23 are arranged to scoop off a portion of the liquid stream flowing thereby, the scooped off portion creating a vortical flow pattern in the semi-circular projection. The center of the vortex creates a negative pressure which provides a suction at respective control ports 25 and 27. The suction aspirates ambient air into the diverter element 10. When both control ports are wide open, pressure in the region of right control portion 27 is more negative than at left control port 25 because of the smaller cross section of right control port 27. More specifically, if both control ports are opened to ambient, less ambient air can flow in through control portion 27 than through control port 25 and therefore the pressure at the right side wall 15 in the vicinity of projection 23 is significantly more negative than the pressure along sidewall 13 in the vicinity of projection 21. The water power stream therefore attaches to sidewall 15 and flows out through passage 33. If left control port 45 is covered or capped ambient air can no longer be aspirated into projection 21, rendering the pressure therein more negative than the pressure in projection 23. The power stream therefore switches, attaching to sidewall 13 and flowing through outlet passage 31 and over the weir 35.

For the most usual irrigation applications of element 10, tubing will be connected to control port 25, and the other end of the tubing will be connected to a liquid level detector in some liquid container or irrigation ditch. When the level in the container or ditch blocks inflow of ambient air through the tubing to control port 25, the power stream switches to outlet passage 31. When inflow through the tubing is not blocked by the liquid level being detected, the power stream flows out through outlet passage 33.

The vortex action associated with projections 21 and 23 permits stronger aspiration of ambient air than is possible in prior art fluidic diverter elements of the aspiration-control type. For example in the liquid level detectors employed in U.S. Pat. No. 3,267,949 the aspiration of ambient air is achieved solely through venturi action resulting at the power nozzle. The aspiration thus produced is satisfactory where the diverter element can be placed relatively close to the liquid level detector. However, for purposes of irrigation systems, the location at which the level is being detected may be on the

order of a hundred or more feet from the location of the diverter element. In most instances, this renders the simple power nozzle venturi action too weak to achieve a position switching action in the diverter element. Consequently the increased aspiration produced by the vortex action in projections 21, 23 is required. Another novel feature of diverter element 10 of FIGS. 1 and 1a is the relatively wide and flat outlet passage configuration which permits issuance of a thin ribbon of water over respective weirs 35 and 37. The need for this configuration relates to the relatively low pressure of the water supplied at inlet opening 17, it being relatively difficult to obtain positive switching of a low pressure head water stream. In a typical embodiment, for a power nozzle width W , the flow divider 29 is located a distance between $4W$ and $6W$ downstream of power nozzle 19, the transverse width of each outlet passage 31 and 33 adjacent the apex of divider 29 is approximately $3W$, and the width of each of outlet passages 31 and 33 at their downstream ends is approximately $4W$. I have found that where the outlet passages are configured substantially narrower than indicated by the aforementioned example, the diverter may become unstable and switch irrespective of variations in the control port flow impedance, or incomplete diversion of the water stream will result. The relatively wide outlet passage permits a better power stream diffusion action and lowers the output flow impedance; in addition the relatively large set back of the downstream portions of sidewalls 13 and 15 permits a greater memory capability for diverter element 10.

It is to be pointed out that aspiration type control of a fluidic diverter element is particularly suited to irrigation systems since the control energy is derived solely from the power stream flow, and therefore auxiliary pressure sources are not required for control purposes.

Referring now to FIG. 2 of the accompanying drawings there is illustrated a fluidic diverter element 10' constructed in a manner similar to diverter 10 of FIG. 1 but configured slightly differently to permit analog or proportional type operation as opposed to the digital or switching operation of diverter 10. Like components in FIGS. 1 and 2 are designated by similar reference numerals, the elements in FIG. 2 being designated with primes. Like diverter 10, diverter 10' has sidewalls 13' and 15' arranged to permit attachment thereto of the power stream. The sole difference in configuration for diverter elements 10 and 10' resides in the greater control port cross section in analog diverter 10'. More specifically, control ports 25' and 27' are of substantially larger cross section than either of control ports 25 and 27. As a consequence, the mass flow rate of ambient air aspirated into diverter element 10' via control ports 25' and 27' is substantially larger than the mass low rate of ambient air aspirated into diverter element 10. Control ports 25' and 27' are made sufficiently large that when both control ports are open excess ambient air flow is aspirated to each sidewall in the proximity of projections 21' and 23'. This greatly weakens the negative pressure characteristic on both sides of the water power stream, with the result that there is little tendency for the power stream to attach to either of the sidewalls. Consequently, if, as assumed here, control ports 25' and 27' have the same cross section, the power stream divides evenly between outlet passages 31' and 33'. If the ambient air inflow through either of control ports 25' and 27' is partially attenuated, as by partial blocking of the control port, the vortical flow in the corresponding projection (21' or 23') regains some of its strength and provides an increasing negative pressure, with the result that the power stream is drawn toward the outlet passage (31' or 33') on the same side of diverter 10' as the attenuated control inflow. The degree of diversion of the power stream is proportional to the difference between control inflow rates at ports 25' and 27'. It is significant that in this approach to analog or proportional type flow diversion an interesting advantage accrues in that both analog and bistable modes operation can be obtained with the same basic element configuration; the operational mode is determined by the size of the control ports. If, as illus-

trated in FIGS. 1 and 2, properly sized removable inserts 26 and 28 (or 26' and 28' in FIG. 2) are provided for respective control ports 25 and 27 (or 25' and 27'), the analog and bistable operational modes may be selectively chosen by merely employing the appropriate inserts. Thus, diverter element 10', having control ports 25' and 27' of relatively large and equal cross sections, can be fitted either with inserts 26' and 28' of relatively large and equal cross sectional openings to permit analog operation; or may be fitted with inserts 26 and 28 of relatively small and unequal (or equal if no bias is desired) cross sectional openings to permit bistable operation. The inserts may threadedly or otherwise, engage their respective projections 21, 21', 23, 23'.

Referring now to FIGS. 3, 4 and 5 of the accompanying drawings there is illustrated a fluidically controlled water gate in accordance with the present invention. The unit comprises a roller curtain gate 40 driven by a fluidically controlled "leaky bucket" actuator 41. Roller curtain 40 is intended to control outflow of a liquid, such as water, contained in a tank 43 having an aperture 45 defined through one of its sidewalls 47. The outside surface of sidewall 47 and attachments thereto are illustrated in FIG. 3 and the inside surface of sidewall 47 and attachments thereto are illustrated in FIGS. 4 and 5. Outflow through aperture 45 may be dumped directly into an irrigation ditch or, as illustrated in FIG. 3, be conducted directly into the inlet opening of a fluidic diverter valve 49 such as the diverter valve illustrated in FIGS. 1 or 2. The roller curtain 40 is constructed of a flexible sheet material of such size and shape to completely cover aperture 45 when the sheet is placed flat over the aperture. A series of closely spaced parallel stiffener elements 51 are secured to the flexible sheet material and extend over a least that portion of the curtain 40 which overlies aperture 45 when the gate is closed. The stiffener elements 51 are wires or rods of metal or plastic of sufficient strength to prevent collapse of curtain 40 when subjected to fluid pressures normally experienced in tank 43 in the vicinity of aperture 45.

The top edge of curtain 40 is secured to the inside surface of sidewall 47 above aperture 45 by any suitable means such as screws 53. The entire bottom edge of curtain 40 is secured to a cylindrical roller 55. A pair of ropes or cords 57 and 59 are secured to the inside surface of sidewall 47 near the top of and behind curtain 40, for example by means of screws 53. Cords 57 and 59 and extend downwardly behind curtain 40, under roller 55 and then upwardly to respective tracks or grooves in a pair of roller elements 61 and 63 located atop sidewall 47. From roller elements 61 and 63, the cords 57, 59 extend downwardly in front of the outside surface of sidewall 47 toward the leaky bucket 41 to which the cords are secured.

The leaky bucket 41 has holes 65 in its bottom and is pivotally mounted about pivot points 67 and 69 to the outer surface of sidewall 47 somewhat above aperture 45. The bucket is pivotable between two extreme positions, in one of which the bucket extends horizontally from wall 47 in right-side-up orientation. In the other extreme position the bucket is rotated downwardly from its horizontal position. Cords 57 and 59 are secured to the bucket at a location substantially displaced from pivot points 67 and 69. It may thus be seen that the cords 57 and 59 support the roller curtain 40 and leaky bucket 41 on opposite sides of wall 47 and that the curtain is actuatable in a manner similar to that in which a conventional porch screen is actuated; more specifically when bucket 41 pivots downward a force is exerted on cords 57 and 59 in front of wall 47, which acts to roll the roller curtain 40 upward to permit outflow of water from container 43 via aperture 45. When the bucket pivots upwardly toward its horizontal position cords 57 and 59 become slack and roller curtain 40 is permitted to unroll and block outflow via aperture 45.

The water pressure inside container 43 seals the roller curtain 40, along its edges, against the inner surface of sidewall 47, assuring that there is no leakage of water from the tank through aperture 45. The forces required to roll the curtain are relatively small as compared with the force required to

pull a cover or valve in a sliding relationship across an aperture such as 45 in a tank. In fact, the primary forces required, except for the elastic restraint in rolling up the curtain, are principally the Bernoulli forces which occur when the roller curtain nearly closes aperture 45.

In the absence of at least a predetermined weight of water or other liquid in bucket 41 the bucket remains substantially horizontal, corresponding to the closed position of the roller curtain gate 40. When the weight of water in the bucket exceeds the predetermined weight, the bucket pivots, and as described above, causes the roller curtain gate to open permitting outflow via aperture 45. Thus, by controlling the amount of water in bucket 41, control of roller curtain gate 40 is achieved. Control over water in the bucket is achieved as follows: A fluidic diverter element 71, for example of the types described in relation to FIGS. 1 and 2 or a more conventional type, is mounted to the outside surface of wall 47 at aperture 45 so as to receive water outflow from container 43 at its power nozzle 72. The water thus received is converted to a power stream of water which can be controllably diverted to either of two outlet passages 73 and 75 by controlling aspiration of ambient air through control ports 77 and 79. When the power stream is diverted to outlet passage 73 it is dumped into the leaky bucket 41, and when it is diverted to outlet passage 75 it is dumped somewhere other than leaky bucket 41, for example to an irrigation ditch fed by diverter 49.

The leaky bucket 41 thus utilizes the weight of water therein to provide an actuating force to raise the roller curtain 40. Bucket 41 is selectively filled by the small diverter valve 71 when the diverter is switched to issue water through outlet passage 73. The water empties slowly through holes 65. Diverter 71 is sized so that its outflow from passage 73 is roughly twice the leakage flow through drain holes 65. The bucket 41 is thus actuated to its extreme downward pivot position in response to outflow from passage 73 of diverter element 71 thereby rolling up curtain 40 and permitting outflow from aperture 45. When outflow from diverter element 71 is through passage 75, leakage through hole 65 permits leaky bucket 71 to assume its uppermost pivot position (horizontal), causing the roller curtain to close and block outflow from aperture 45.

The above described roller curtain concept represents a departure from the pure fluidic (no moving parts) approach associated with the remaining aspects of the present invention; however, it can easily be understood that the mechanical details of the roller curtain control are fundamentally simple, reliable, and inexpensive and that fluidic control of the leaky bucket position is simply achieved. It should also be noted that both the roller curtain gate and the leaky bucket actuating approach can be utilized independent of one another and have individual utility when employed with conventional sensing, actuating, and/or flow modulating devices. For example, the roller curtain may employ actuators for rolling and unrolling curtain 40 sideways rather than up and down.

It should also be noted that, in order to conserve water, the water which leaks through the drain holes 65 in leaky bucket 41, and the water which is dumped from outlet passage 75 of diverter element 71 can be dumped directly into a main irrigation ditch such as a ditch fed by either outlet passage of diverter 49. The utilization of diverter element 49 at aperture 45 is optional depending upon system requirements as regards the outflow from aperture 45.

Referring now specifically to FIG. 6 of the accompanying drawings there is illustrated in schematic form an alternate method for controlling the actuation of a roller curtain water gate. In the arrangement illustrated in FIG. 6 the actuating mechanism is completely contained within the water container 43. As is the case with the embodiment illustrated in FIG. 3, the roller curtain 40 has one edge secured to the inside surface of the sidewall 47 and is positioned so as to be selectively rolled and unrolled over aperture 45. A bucket 81 is secured at its bottom to a fork link member 83 disposed within container 43 and pivoted at one end about a fixed pivot point

85. The opposite end of fork link member 83 contains two prongs, each of which engages a respective end of curtain roller 55. The arrangement is such that when fork link member 83 is horizontal the roller 55 is forced by member 83 to roll up and permit outflow from the container via aperture 45. When fork link member 83 pivots downwardly about pivot point 85 the roller 55 is forced to roll downwardly causing the roller curtain 40 to unroll and cover the aperture 45 in sealing relationship with wall 47.

The sidewall of bucket 81 extend above the maximum water level in container 43. Inflow of water into bucket 81 is controlled by means of a fluidic diverter element 87 mounted within bucket 81 and having its power nozzle inlet opening communicating with the water of container 43 via an aperture 89 defined through a wall of bucket 81. Water supplied to element 87 is selectively diverted to either of diverter outlet passages 89 and 91 by conventional control means such as aspiration control tubes 86, 88 communicating with respective control ports. When the water is diverted to outlet passage 91 it is dumped into bucket 81. When the water is diverted to outlet passage 89 it is conducted by a flexible tubing 90 through the walls of both the bucket 81 and container 43 to the irrigation ditch 92. A bucket drain opening 93 is defined through a wall of bucket 81 near its bottom and serves, via flexible tubing 94, to drain liquid from the bucket to ditch 92. A flotation collar 95 is secured to the exterior of bucket 81 to provide the necessary buoyancy for preventing downward pivoting of the fork link member 83 when bucket 81 is empty. When the bucket 81 is filled to a predetermined level, the weight of the water contents causes the fork link member 83 to pivot downwardly which causes curtain 40 to unroll over aperture 45 and shut off the main water outflow to the diverter element 49.

As was the case with the embodiment illustrated in FIGS. 3 and 4, the inflow rate of bucket 81 via outlet passage 91 of diverter elements 87 is approximately twice the outflow rate from bucket 81 via drain opening 93. When it is desired to close the roller curtain gate, flow from diverter element 87 is directed to outlet passage 91 causing the bucket 81 to take on sufficient water to cause the fork link member 83 to pivot downwardly about pivot point 85. When it is desired to open the roller curtain gate the outlet flow from diverter element 87 is diverted to outlet passage 89 permitting the bucket 81 to empty via drain opening 93. The buoyancy provided by flotation collar 95 causes the bucket 81 and the fork link member 83 secured thereto to be restored in their horizontal position. It is to be noted once again that the drain water from both the pilot or control diverter element 87 and the bottom of bucket 81 is dumped into an irrigation ditch 92 being fed by outflow from aperture 45.

Referring now specifically to FIG. 7 of the accompanying drawings, there is illustrated in diagrammatic form the roller curtain gate and control arrangement described in reference to FIGS. 3, 4, and 5 employed as a level control in an irrigation ditch. Specifically, the left control nozzle 77 of pilot diverter element 71 is in fluid communication with an inverted level sensing cup 101. Level sensing cup 101 is supported in an inverted position over an irrigation ditch 103 with the mouth of the cup positioned at a desired water reference level A-A¹. The arrangement of FIG. 7 prevents the water level in ditch 103 from becoming higher than reference level A-A¹. A fluid passage or tubing 105 communicates between the interior of inverted cup 101 and left control nozzle 77. The right control nozzle 79 is provided with a bias restriction 107 to restrict aspirated air inflow to diverter element 71 via nozzle 79. In this manner, when the water level in irrigation ditch 103 is below reference level A-A¹, the rate of aspirated air inflow through cup 101 and into control nozzle 77 exceeds the rate of aspirated air inflow into control nozzle 79. The power stream in diverter element 71 therefore is directed through right outlet passage 73 and into the leaky bucket 41. The bucket begins to fill and eventually is caused to pivot downwardly whereby roller curtain 40 opens to permit outflow from container or

reservoir 43 via aperture 45 into the irrigation ditch 103. When the water level in irrigation ditch 103 reaches reference level A-A¹, air inflow into inverted level sensing cup 101 is blocked by the water. Air inflow via right control nozzle 79 thus exceeds air inflow via left control nozzle 77 causing the power stream to switch to left outlet passage 75. The bucket 41 is thus permitted to empty via drain holes 65 and the weight of roller 55 and curtain 40 permit the later to unroll while the bucket 41 pivots upwardly. Aperture 45 is now blocked.

10 It is to be noted that outflow via aperture 45 from container 43 greatly exceeds the drain flow from outlet passage 75 of diverter element 71 and the leak flow through leakage holes 65 in leaky bucket 41. In fact the latter two flows are relatively 15 insignificant as compared to the outflow from aperture 45 so that the leakage and drain flows produce no significant rise in the water level in irrigation ditch 103.

15 It should be pointed out that the arrangement of FIG. 7 could readily be used to monitor the water level in container 43 rather than in irrigation ditch 103. By simply supporting the inverted sensor cup 101, with its mouth at the desired level, outflow via aperture 45 from tank 43 can be controlled to keep the container water level at or below that desired level. In this case blockage of aspiration through the sensor cup would initiate water flow to bucket 41 via diverter 71 and inflow from the sensor cup would prevent filling of the bucket.

20 Referring now specifically to FIG. 8 of the accompanying drawings, there is diagrammatically illustrated an alternate scheme for controlling the level in an irrigation ditch. In this embodiment water from container 43 issues from aperture 45 in wall 47 and is conducted to a supply inlet 111 of a fluidic vortex amplifier 113. Vortex amplifier 113 is a conventional, cylindrically configured element having an axially oriented outlet 115, a radially oriented supply flow inlet 111, and a tangentially oriented control flow inlet 117. A bistable fluidic pilot diverter 119 receives pressurized fluid, for example from container 43, and provides a power stream which is selectively diverted to either of outlet passages 121 and 123. Outlet passage 121 of pilot diverter 119 is connected to the tangential control flow inlet 117 of vortex amplifier 113; the flow from outlet passage 123 of diverter element 119 is dumped into irrigation ditch 125. Once again, the fluid flow through diverter 119 is significantly less than through aperture 45. 25 Switching control for diverter 119 is accomplished in the same manner as switching control of diverter element 71 in FIG. 7. Specifically, left control nozzle 127 aspirates air through an inverted level sensor cup 129 having its mouth or rim supported at reference level A-A¹. Right control nozzle 131 is restricted to a greater extent than is left control nozzle 127 so that diverter 119 is normally biased to provide outflow from outlet passage 123.

30 The operation of the vortex amplifier 113 is well known. If control flow is absent, the supply flow applied to supply inlet 111 proceeds directly through outlet 115 in a radial direction 35 through the cylindrical interior of amplifier 113. Outflow from outlet 115 is dumped into irrigation ditch 125. If control is introduced via inlet 117, the momentum exchange between the supply and control flows imparts a tangential component 40 to the supply flow which then must reach the outlet 115 by a spiral or vortical rather than a radial path. This flow increases in tangential velocity by coriolis acceleration and also greatly increases in centripetal acceleration toward the center of the vortical path. The centripetal acceleration thus provides a 45 considerable flow impedance to fluid approaching outlet 115, decreasing the outflow with increasing control flow. The change in outlet flow is essentially inversely proportional to the control flow. Vortex amplifiers can be designed to give maximum to minimum outflow ratios on the order of 10, thereby providing a very useful proportional flow control 50 capability. Thus, when the water level in irrigation ditch 125 achieves level A-A¹, aspirated air inflow to control nozzle 127 of diverter element 119 is blocked causing the power stream diverter element to switch to outlet passage 127 and control inlet 117 of vortex amplifier 113. The resulting regula-

tory action of the supply flow in the vortex amplifier proceeds as described above. It will be appreciated that diverter element 119 may operate in either a bistable or proportional mode.

As will be described subsequently in relation to FIG. 12, one aspect of the present invention contemplates level sensing with a slotted inverted sensor cup whereby aspirated air inflow to a diverter control port is rendered proportional to the sensed liquid level rather than merely being present or absent, at any given instant of time. If such a proportional level sensor is employed, the diverter element 119 may be a proportional type fluidic amplifier, for example diverter 101 of FIG. 2, which in turn acts to proportionally throttle the flow between reservoir or container 43 and irrigation ditch 125 via vortex amplifier 113.

Referring now specifically to FIG. 9 of the accompanying drawings there is illustrated diagrammatically a fluidically controlled siphon arrangement by means of which water or liquid in a container or reservoir 135 can be selectively made to flow to a desired location, for example to an irrigation ditch. Siphon 137 comprises a tube having its open upstream end in fluid communication with water in reservoir 135, either through an appropriate opening in a wall of the reservoir as illustrated, or by extending over the top of the reservoir wall. The siphon tube has an inverted generally U-shaped configuration with a short horizontal section at its upstream end. The apex or gooseneck section of the siphon tube extends to a height which is above the maximum water level in reservoir 135. The downstream end of the siphon tube extends into a catch basin 139 having a main discharge of flume 141 which permits egress of water from the catch basin whenever the water level exceeds the level at the mouth of the flume. The downstream end of the siphon tube extends into catch basin 139 below the level of the mouth of flume 141.

A bistable fluidic pilot diverter valve 143 receives water under pressure from reservoir 135 at its power nozzle 145 via an appropriate opening or aperture in the sidewall of the reservoir. Diverter valve 143 has respective left and right control ports 147 and 149 of the aspiration type and left and right output passages 151 and 153 respectively. Outlet passage 153 is arranged to discharge water received thereby directly into catch basin 139. Outlet passage 151 is provided with a venturi section 155 at its downstream end which is also arranged so that water received by outlet passage 151 is discharged into the catch basin 139. The neck of venturi section 155 is in fluid communication with the interior of siphon 137 at the apex or gooseneck of the latter by means of a suction tube 157.

In operation, when right control port 149 is blocked and left control port 147 is open to permit aspiration of air to element 143, the water power stream discharges from right outlet passage 153 into the catch basin 139. Water in the catch basin eventually covers the downstream end of the siphon. The catch basin continues to fill until the water overflows the discharge flume 141. The water level in the siphon on the upstream side of the siphon gooseneck adjusts to water level in reservoir 135.

When the left control port 147 is blocked and aspiration of air is permitted only through right control port 149 the power stream flow in diverter element 143 issues from left outlet passage 151 into catch basin 139 via venturi section 155. Power stream flow through the venturi section causes a suction or negative pressure in suction tube 157 which draws air from the top of the gooseneck section of the siphon, raising the water level therein in both the upstream and downstream sections. When the level in the upstream section of the siphon 137 rises over the gooseneck section, flow between the reservoir 135 and catch basin begins. With continued aspiration by means of venturi section 155 the siphon achieves full flow.

If now left control port 147 is opened and the right control port 149 is blocked the fluidic element again switches away from venturi section 155 to outlet passage 153. Ambient air now flows into the downstream end of venturi section 155 and through suction tube 157 to the siphon gooseneck, increasing the pressure thereat and terminating siphon flow.

It is noted that both outlet passages 151 and 153 of pilot diverter 143 are arranged to discharge fluid into catch basin 139. This is required to maintain the downstream end of the siphon 137 under water so that air can be drawn out of the siphon gooseneck when desired. It is also important that the venturi section of outlet passage 151 be at least partially elevated from the quiescent water level in the fluidic diverter element 143 so that air can enter suction tube 157 and flow to the siphon gooseneck when the diverter element switches to outlet passage 153. It is this air which, upon entering the downstream end of venturi section 155, increases the interior pressure in the siphon sufficiently to stop siphon flow. A further consideration to bear in mind is that the pilot diverter element 143 runs continuously so that its output flow should be kept a minimum.

I have found that the negative pressure or suction which can be generated in the venturi section 155 is approximately fifty to sixty percent of the positive pressure head available at the power nozzle 145. This of course provides a limit as to the height to which water can be raised in the siphon by the suction action of the venturi section.

The fluidically controlled siphon can be modified for proportional flow control as well as on-off control. For example, if fluidic element 143 is of the analog or proportional type, the negative pressure generated in the venturi section 155 varies proportionally with flow therethrough. Consequently the height to which water can be drawn over the siphon gooseneck is proportional to power stream flow in outlet passage 151. In such an arrangement, the water velocity through the gooseneck section of the siphon 137 should be kept sufficiently low in order that water flow does not entrain air in the top of the gooseneck. The latter condition would cause the siphon to run at full flow rather than as a controlled proportional function of flow diversion in element 143.

Referring now to FIG. 10 of the accompanying drawings there is illustrated a modification of the arrangement of FIG. 9 whereby the siphon gooseneck or arch is capable of being swiveled to provide an adjustable gooseneck height. The only substantial difference in the arrangements between FIG. 9 and FIG. 10 therefore resides in the provision of two rigidly supported fluid fitting members 161 and 163 which are adapted to receive, in fluid-tight relation, the respective upstream and downstream ends of the gooseneck section of siphon tube 137.

The gooseneck section is rotatable in both of the fluid fitting members 161 and 163 so that the height of the gooseneck may be selectively adjusted. The suction tube 157 connecting the siphon arch and the venturi section 155 is of course made flexible in order to accommodate the various possible positions of the movable siphon arch. Upstream fitting member 161 provides fluid communication between the gooseneck section and reservoir 135 via the upstream section of the siphon. The downstream fitting member 163 provides fluid communication between the gooseneck and the catch basin 139 via the downstream section of the siphon.

In operation, the arrangement of FIG. 10 performs identically to the arrangement of FIG. 9 except that the arrangement of FIG. 10 is able to perform in response to lower flow rates through venturi section 155 of elements 143. More specifically, by lowering the siphon arch sufficiently, the water in the siphon can be raised to permit the siphon flow even when the pressure head applied to the diverter element is relatively low.

Referring now to specifically to FIG. 11 of the accompanying drawings there is illustrated in diagrammatic form an alternate arrangement for fluidically controlling siphon flow. In order to eliminate the venturi section 155 in FIGS. 9 and 10, diverter element 143 is replaced by diverter element 165 which is of the type described above in relation to FIG. 1. As is the case with the arrangement of FIG. 9, the siphon tube 137 has its upstream end communicating with the liquid contents of reservoir 135 and its downstream end disposed in catch basin 139. Diverter element 165 has its inlet opening communicating with the liquid in reservoir 135 and the pressurized liquid is selectively discharged through either of outlet

passages 167 or 169 into catch basin 139. A standpipe 171, comprising a hollow tube, is located with its open bottom end near the exit of outlet passage 169. More specifically the bottom end of standpipe 171 is disposed slightly above the top of the downstream weir 173 in passage 169. Standpipe 171 communicates directly with suction tube 157 which, as described in relation with FIG. 9, communicates with the top of the gooseneck of siphon tube 137. In addition, left control port 175 of diverter 165 communicates via fluid passage 177 with a junction between the stand pipe 171 and suction tube 157.

It is important that the bottom of the standpipe 169 be disposed slightly above the weir 173 so that when diverter flow issues from outlet passage 167 air can enter the standpipe and flow to the siphon gooseneck to stop siphon flow. If the standpipe extended below the weir 173 the residual water level of the diverter element 165 would block the bottom of the standpipe, even without flow through passage 169, and thereby block the required air flow. When diverter flow issues from passage 169 the water covers the bottom of the standpipe preventing any substantial air flow into suction tube 157 from standpipe 171.

The operation of the arrangement in FIG. 11 is as follows: When right control port 179 of diverter element 165 is initially uncovered, there is no siphon flow. Water entering the diverter element 165 initially tends to divide between the outlet passages 167 and 169 because of relatively equal air flows entrained into both control ports 179 and 175. As air is drawn from the siphon arch into left control port 175 via passage 177 and suction tube 157 and into standpipe 171 via suction tube 157, the flow in diverter element 165 gradually switches to left output passage 169. More particularly, the inflow to control port 179 remains substantially the same whereas the inflow to control port 175 gradually decreases as more and more of the limited air supply is sucked out of the siphon gooseneck. As more flow switches to left outlet passage 169 the suction capability of control port 175 increases due to the increasing vertical flow in the vortex projection associated with control port 175. The increasing suction raises a column of water in standpipe 171. When enough air is drawn from the siphon 137 water flows over the gooseneck and siphon flow begins. As the flow in the siphon increases, the remaining air in the siphon is washed out by the water flow and the siphon achieves the full flow mode.

When right control port 179 of diverter 165 is blocked, air flow thereinto stops and the power stream begins to switch toward outlet passage 167. When the switching is nearly completed, the water level in outlet passage 169 drops below the bottom of standpipe 171 permitting air to enter the standpipe and be entrained by siphon flow into the siphon via suction tube 157. Air entering standpipe 171 is also entrained into control port 175 assuring that the diverter flow remains directed toward outlet passage 167. The air entering the siphon gradually increases the pressure therein and terminates siphon flow.

As mentioned above, the siphon arrangement illustrated in FIGS. 9, 10 and 11 need not communicate through a all of the reservoir but instead may be disposed so that the siphon gooseneck straddles the reservoir wall. There is no substantial change in the operation of such an arrangement as compared with the arrangements illustrated in FIGS. 9 through 11.

Referring now specifically FIG. 12 of the accompanying drawings there is illustrated a proportional type fluidic liquid level control arrangement. A fluidic analog diverter 180 of the type illustrated in FIG. 2 distributes its outlet flow between left and right outlet passages 181 and 183 as a proportional function of the liquid level in a container 185. In the particular arrangement chosen for illustration in FIG. 12, outlet flow from right outlet passage 183 is issued into container 185 and outlet flow from left outlet passage 181 is issued into a bypass flow channel 187. By virtue of this arrangement, the liquid in the container is maintained at a desired level even as liquid is withdrawn from the container. A left control port 189 communicates by means of tubing 191 with an inverted level

sensing cup 193. The mouth of cup 193 extends downwardly into container 185 to some desired depth. The cylindrical sidewall of cup 193 has multiple slots defined through most of its length. Right control port 195 of diverter element 180 serves as a bias port and in this regard is somewhat smaller in cross section than control port 189.

When tank 185 is empty, air is aspirated via the mouth and slots of sensor cup 193, through tubing 191, into left control port 189. Since the ambient air inflow to left control port 189 is larger than to the smaller right control port 195, substantially more of the power stream water flows through right output passage 183 than through left output passage 181. As the water level in container 185 rises, the aspirated air flow into left control port 189 decreases because the rising water level gradually decreases the area through which air can pass into sensor cup 193. Decreased inflow of air into control port 189 causes the power stream to deflect more towards left output passage 181. By properly correlating the cross sectional openings of control ports 189 and 195, the power stream flow in element 180 can be designed to issue entirely from left output passage 181 when the liquid in container 185 achieves a predetermined level. Thus, as the liquid is utilized or otherwise withdrawn from container 185, the flow in element 180 is correspondingly proportioned between output passages 181 and 183 to maintain the desired container water level.

The proportional or analog liquid level control concept embodied in FIG. 12 is readily adaptable to the level control arrangements described above in relation to FIGS. 7 and 8 by simply employing slotted sensor cups and proportional diverter element.

In addition to slotting the sidewall of the sensor cup, proportional or analog sensing of liquid level may be achieved by providing a sensor cup with one or more vertical rows of small holes. In this case as well as the slotted configuration, a rising level gradually decreases the area through which the aspirated air can enter the cup.

Referring now to FIG. 13 of the accompanying drawings there is diagrammatically illustrated an arrangement for sensing the water level in an irrigation ditch 203. The sensor comprises a shallow basin 201 placed in the ditch and having inlet leakage holes 205 defined through its sidewall near the bottom of the basin. An inverted level sensor cup 207 is disposed with its mouth supported at a predetermined level in basin 201. The cup has a sufficiently large diameter to prevent capillary action from keeping water in the cup when the water level in the basin drops below the cup mouth or rim. The closed end opposite the mouth of the inverted cup 207 communicates via tube 209 with the control port of a fluidic diverter element such as is employed in FIG. 1 and which controls flow to one or more irrigation ditches, including ditch 203. When the water level in basin 201 reaches the mouth of cup 207, the water level in cup 207 is raised by the aspiration action associated with the control port of the diverter element.

When water rises in cup 207 the supply of aspirated air to the diverter element via tube 209 is terminated causing the diverter element to switch and terminate the supply of water to irrigation ditch 203. The purpose of the shallow basin 201 is to minimize currents in the vicinity of the rim of the cup 207 so as to improve the sensitivity of the cup and prevent cut-off of aspirated air by waves occurring in the ditch 203. It is apparent that by adjusting the height of the cup rim it is possible to vary the maximum depth to which irrigation ditch 203 is to be filled.

It is important that the height of the cup be sufficient to provide an air dome above the air level in the sensing cup. The water level is thus permitted to rise a few inches inside the cup but does not enter the air line 209 to the control port of the diverter element. Water in line 209 would tend to clog the line and prevent reliable switching action at the diverter element.

In a practical application of the arrangement in FIG. 13, basin 201 is placed at or proximate the downstream end of ditch 203 to assure that the water has achieved the desired level throughout the entire length of the ditch. When the ditch

is relatively long, a long length of tubing 209, required to interconnect the sensor cup 207 with the diverter element control port. Too long a tubing can result in intolerable pressure losses which substantially minimize the effects of the control port aspiration. Therefore for very long ditches the sensing arrangement in FIG. 13 sometimes proves unsatisfactory. To overcome this problem the sensing arrangement illustrated in FIG. 14 is provided. The arrangement in FIG. 14 is designed to be placed near the diverter at the upstream end of ditch 213, thereby solving both the expense and pressure drop problems arising from long lengths of tubing 209. The arrangement in FIG. 14 includes a shallow basin 211 disposed near the upstream end of irrigation ditch 213 and having a number of inlet leakage holes 215 defined through its sidewall near the bottom of the basin. An inner basin 216 is disposed within basin 211 and has a relatively small inlet orifice 218 by which water in basin 211 is permitted to enter basin 216. A sensor cup 217 is inverted with its rim supported at a predetermined level in inner basin 216. A relatively short length of tubing 219 communicates between sensor cup 217 and a diverter element control port.

The size of inlet orifice 218 of basin 216 is chosen so that the time taken for water to rise to the mouth of cup 217 in inner basin 216 corresponds to the time taken for water at the downstream end of irrigation ditch 213 to achieve the desired level. The sensor cup is thus placed much closer to the diverter than is the case for the arrangement in FIG. 13; however the sensor cup 217 still provides a measure of liquid level at the downstream end of irrigation ditch 213.

Referring now to FIG. 15 of the accompanying drawings there is illustrated a further level sensor for use in detecting when the water in an irrigation ditch 223 achieves a predetermined level. A vertically disposed stake 221 is anchored beneath the bottom of irrigation ditch 223. A shallow basin or bowl 225 slidably engages stake 221 and may be secured by means of adjustment screw 227 at any desired depth in ditch 223. Basin 225 has a cover plate 229 over its top, the cover plate having a plurality of apertures 231 permitting ingress of water into the basin when the water level in ditch 223 overflows the top of the basin. An inverted sensor cup 235 is disposed with its rim extending into basin 225 through a further opening in cover plate 229. The depth to which the rim of sensor cup 235 extends into basin 225 is adjustable by simply sliding the sensor cup 235 relative to cover the plate at 229. A fluid passage 237 interconnects the interior of sensor cup 235 to a control port of a fluidic diverter, for example of the type disclosed in FIG. 1.

In operation, assume that both ditch 223 and basin 225 are empty of water. Air flows into the basin 225 via openings 231 due to the aspiration action at the control port of the fluidic diverter connected to passage 237. Assuming that inflow of aspirated air into the diverter in this manner causes water to flow into ditch 223, the water level in ditch 223 gradually rises. At some point the water level in the ditch overflows the top of basin 225 and enters the basin via inlet holes 231. Filling of ditch 223 continues until the water level in basin 225 reaches the rim of inverted sensor cup 235, cutting off air flow into the sensor cup and causing the diverter to terminate water flow to irrigation ditch 223. The maximum depth of the water in the irrigation ditch is thus determined by the top or rim of basin 225.

Water in the irrigation ditch is absorbed by the soil. However, the water in basin 225 evaporates slowly, at the rate of approximately one-fourth inch per day (depending upon the various weather conditions). When the water level in basin 225 evaporates sufficiently to permit air flow to enter the inverted sensor cup 235, the diverter is switched to cause water to flow into irrigation ditch 223. It may thus be seen that the vertical distance, x in FIG. 15, between the top or rim of basin 225 and the mouth or rim of inverted sensor cup 235 determines the re-cycle time for flow into ditch 223. More specifically, if it is desired to fill ditch 223 every second day, the distance x is chosen to be one-half inch, and the evaporation

rate of approximately one-fourth inch of water per day from the basin 225 produces the desired filling ditch 223 on alternate days.

It is to be understood that the level adjustment for basin 225 in FIG. 15, namely stake 221 and adjustment screw 227, can be utilized in conjunction with basin 201 and basin 211 in FIGS. 13 and 14 to provide adjustable depth sensing in the irrigation ditches 203 and 213.

Referring now specifically to FIG. 16 of the accompanying drawings there is illustrated in diagrammatic form a level sensor of the type described in relation to FIG. 15, modified to include a built-in rainfall override for minimizing filling of an irrigation ditch during periods of time where rainfall has supplemented the irrigation burden. More specifically, a basin 241 of the type similar to basin 225 in FIG. 15 is disposed at a preselected depth in ditch 243. An inverted sensor cup 245 is mounted to extend through cover plate 247 of basin 241 so that the rim of the sensor cup extends into the basin. A plurality of inlet openings 249 permit ingress of water and air to the interior of basin 241, and a section of tubing 251 communicates with a fluidic diverter control port as described in relation to FIG. 15.

A roof or roof-like structure 253 is disposed above the entire basin 241. A rain collection pan 257 is provided atop the roof and, as illustrated, may be constructed integrally with the roof. The bottom of the pan slopes downwardly from its sides to form a drain funnel having a spout 259 disposed to issue water collected by pan 257 into basin 241. In this way rain collected by pan 257 adds to the water level inside basin 241 to modify the filling cycle of ditch 243 as a function of rainfall. The sensitivity of the rainfall override in providing additional time delay between diverter operations is determined by the area ratio between rain collection pan 257 and the basin 241. More specifically, the greater the surface area of pan 257 relative to the surface area of evaporation pan 341, the greater is the delay in actuating the fluidic diverter element to fill ditch 243 in response to a given amount of rainfall.

The various level sensors thus far described are extremely simple; however, as described above in relation to FIG. 14, there is a limitation in the application of these sensors as determined by the pressure losses occurring in tubes 209, 237 and 251 interconnecting the various level sensor cups with the control ports of fluidic diverter elements. FIG. 14 offers one approach to overcoming this problem; namely, employing a delay scheme for simulating the level at the downstream end of an irrigation ditch with an apparatus positioned adjacent the upstream end of the ditch. Another approach is to use a two stage diverter scheme of the type illustrated in FIG. 17. In this type of arrangement, separations between the diverter and sensor on the order of 800 to 1,000 feet can be tolerated. As illustrated, this scheme employs a fluidic pilot diverter element 260 connected in cascade with a main fluidic diverter 270. The pilot diverter element 260 is relatively small; of necessity diverter element 260 is sufficiently small to render it sensitive to the low negative pressure levels received via sensor communication tubing 261. Tubing 261 communicates with the right control port 263 of diverter element 260. Left control port 265 has a smaller cross section than right control port 263 and serves to bias power stream flow from power nozzle 264 toward the left outlet passage 266. The pressurized power stream fluid is received from a reservoir or container of water which is to be selectively fed either to an irrigation ditch 280 or a bypass channel 281.

Diverter elements 260 and 270, may by way of example only, be of the types described in relation to FIGS. 1 and 2 herein but of course must be of substantially different sizes.

Left output passage 266 of diverter element 260 dumps fluid issuing therefrom into a relatively small upright cup 268, the bottom of which communicates directly with the left control port 271 of diverter element 270. Small cup 268 is supported interiorly of a larger cup 269 so that the latter receives liquid overflow from the small cup 268. Such overflow is dumped into the left output passage 272 of diverter element

270 and flows to irrigation ditch 280 along with power stream flow in left output passage 272.

A similar arrangement exists at the right control nozzle 273 of diverter element 270 in that the right outlet passage 267 of diverter element 260 dumps fluid flowing therein into a small cup 274. The bottom of cup 274 communicates directly with right control nozzle 273 and small cup 274 is supported interiorly of a larger cup 275 which receives liquid overflow from small cup 274. Such overflow is conducted from larger cup 275 into right outlet passage 276 of diverter element 270 and flows to bypass channel 281 along with power stream flow conducted through right outlet passage 276.

In operation, assume that a level sensor of the type illustrated in FIG. 13 is disposed at the downstream end of irrigation ditch 280, and that tubing section 209 in FIG. 13 is identical to sensor line 261 in FIG. 17. When the level of the liquid in ditch 280 is below the desired level, air is conducted along sensor line 261 to right control port 263. Pressure losses are substantial over such a long length of sensor line 261 but because of the small size of diverter element 260 the latter is sufficiently sensitive to aspirated air inflow at control port 263 to cause the water power stream to flow through left outlet passage 266. This water outflow is dumped into cup 268 and blocks air flow into left control nozzle 271; however there is no water in cup 274 to block aspirated air inflow into right control port at 273. Consequently the water power stream in diverter element 270 switches to left output passage 272 and is directed into irrigation ditch 280. It is noted that the water overflow from cup 268 into cup 269 flows along with the power stream in left outlet passage 272 into irrigation ditch 280. In addition, water in cup 268 is conducted to left control nozzle 271 where it joins the power stream and also flows to ditch 280.

When the water level in irrigation ditch 280 achieves the predetermined reference level determined by the sensor of FIG. 13, aspirated air flow through sensor communication line 261 terminates. Aspiration through left control port 265 of pilot diverter element 260 now exceeds that through right control port 263 and the power stream in element 260 switches to the right outlet passage 267. Flow in outlet passage 267 is directed into small cup 274 to block aspirated air inflow into right control nozzle 273 of diverter element 270. On the other hand, with the termination of outflow from outlet passage 266 of diverter element 260, there is no longer any water present in cup 268 and aspirated air inflow begins into left control nozzle 271. In response to these changes and conditions at the control nozzles, diverter element 270 switches so that the power stream exits from right outlet passage 276 into bypass channel 281.

For the arrangement illustrated in FIG. 17, sensor separation distances from the diverter on the order of 800-1,000 feet are practical with communication line diameters on the order of one-fourth inch diameter.

Referring now specifically to FIG. 18 of the accompanying drawings there is illustrated still another arrangement whereby the problems associated with long distances between the level detection apparatus and the fluidic diverter are overcome. In the arrangement in FIG. 18 the flow into an irrigation ditch 285 is automatically turned off after a predetermined volume of water has issued into that ditch. A fluidic diverter element 287, for example of the type illustrated in FIG. 1, receives pressurized water at its inlet opening and selectively distributes it to either of right or left outlet passages 289 and 291. Right outlet passage 289 feeds irrigation ditch 285 and left outlet passage 291 feeds irrigation ditch 293. Right control port 295 has a relatively small cross section and serves as a bias control port for diverter 287. Left control port 297 has a somewhat larger cross section than right control port 295 and has one end of a sensor communication tube 299 connected thereto. The other end of tube 299 extends to a predetermined depth in a sensor cup 301, the bottom of which drains at an adjustable flow rate into the soil through an orifice which is adjustable in size by means of an adjustment control 303. A

flow sampling tube 305 communicates between right outlet passage 289 and metering cup 301 so that a small predetermined proportion of water egressing from outlet passage 289 is supplied to metering cup 301.

In operation, when the water in metering cup 301 is below the level of sensor communication tube 299, full air flow is aspirated into control port 297 and the power stream in element 287 flows through right outlet passage 289 into ditch 285. The small predetermined proportion of the right outlet passage flow is directed via sampling tube 305 into the metering cup 301 which gradually fills until such time as sensor communication tube 299 is blocked. When tube 299 is blocked the element 287 switches to provide water to ditch 293 via outlet passage 291.

It can be seen from the above description that the length of time during which element 287 supplies water to ditch 285 is determined by the time required to fill metering cup 301; the latter time in turn is determined by the amount of water flowing through outlet passage 289 into ditch 285 in a given cycle. The rate at which metering cup 301 fills may be varied by adjustment control 303 and therefore the amount flow permitted to ditch 285 at any given cycle is adjustable.

In some irrigation applications, in order to conserve water, it is desirable that the cycling of water flow into an irrigation ditch be controlled to some extent at least by the moisture content of the soil. For example, a level sensor in an irrigation ditch may indicate that the water level in that ditch is below a desired reference level; however, the soil may still be saturated with moisture and additional inflow to the irrigation ditch would be wasted in part due to evaporation. In the arrangement schematically illustrated in FIG. 19 a soil moisture override is utilized in conjunction with a liquid level sensor to control water supply to an irrigation ditch. A diverter element 307, for example of the type illustrated in FIG. 1, is supplied with pressurized water at its power nozzle 309 which in turn issues a power stream of water into either of left or right output passages 311 and 313. Outlet passage 311, for example, may feed the irrigation ditch and outlet passage 313 may feed a bypass channel. Left control port 315 is of relatively small cross section and serves as a bias port in the arrangement of FIG. 19. Right control port 317 is somewhat larger in cross section and acts to aspirate air into diverter 307 through each of two air lines 319 and 321. Air line 321 communicates with a liquid level sensor, for example of the type disclosed in FIG. 13 above, which monitors the level in the irrigation ditch supplied by left outlet passage 311. Air line 319 is fed by a soil moisture detector unit 325. Unit 325 comprises a container 327 constructed of plastic, metal or similar material. A small portion of container 327 extends above the ground level 329 and has a funnel 331 extending upwardly therefrom. Funnel 331 serves to collect rain water, and is provided with a relatively small discharge opening 333 through which the rain water empties into container 327. The relatively small opening 333 is required to minimize evaporation of moisture from within container 327.

Disposed within container 327 is a mass of porous material 335 which fills a substantial portion of the container. A drain opening 337 at the bottom of the container permits excess water collected in the container to seep into the soil.

A sensor opening 339 is provided in the side of container 327 and communicates directly with air line 319 and in turn with right control port 317 of fluidic diverter element 307. Interiorly of container 327, the region immediately surrounding sensor opening 339 is blocked by a fine mesh screen 341 which prevents the porous material 335 from entering air line 319. Mesh screen 341 is disposed so as to be entirely surrounded by the porous material 335.

The relative sizes of control ports 315 and 317 of diverter element 307 are adjusted so that in normal operation part of the aspirated air required to switch the water power stream into left outlet passage 311 must come from the soil moisture sensor 325. More specifically, the air provided by the liquid level sensor 323 via air line 321 of itself is insufficient to over-

come the effect of aspirated air inflow into bias control port 315. Similarly, the air inflow provided from moisture level sensor 325 of itself is less than the aspirated air inflow into bias control port 315. Diverter 307 may therefore be said to operate an AND logic wherein both the level sensor 323 and the soil moisture sensor 325 must supply air before the diverter element switches to passage 311.

If excess water is present in the soil then the porous material 335 in the container 327 becomes saturated and air cannot flow from the funnel through the saturated porous material. Air line 319 is thus blocked and the power stream in element 307 is diverted to the bypass channel via outlet passage 313. When the soil is relatively dry, moisture in container 327 drains through opening 337 unsaturating the porous material 335, and permitting air to flow through funnel 331 to air line 319. In this condition the liquid level sensor 323 determines the switching state of diverter element 327 in accordance with the level in the ditch being monitored.

The porous material 335 can be any material suited for the purpose described above and preferably is chosen to match the local soil drainage characteristics.

Another ambient condition, in addition to soil moisture content, which is to be considered for purposes of controlling irrigation cycles is ambient temperature. When the ambient temperature drops below freezing it is desirable to prevent flow into an irrigation channel. Similarly, it may be desirable to cut off irrigation flow for high temperatures to avoid excessive evaporation of water from the irrigation ditch. In the arrangement illustrated schematically in FIG. 20 the diverter control circuit includes a temperature override sensor comprising a bi-metallic strip 345. One end of the bi-metallic strip 345 is ridgedly mounted and the other end is free and provided with a plug 347 adapted to selectively block and unblock air flow through opening 349 of air line 351 in response to temperature changes causing pivotal motion of bi-metallic strip 345 about its fixed end. The remaining portion of the arrangement illustrated in FIG. 20 is substantially identical with the arrangement illustrated in FIG. 19, with the soil moisture override 325 in FIG. 19 replaced by the ambient temperature override 345 in FIG. 20. Identical reference numerals are employed in FIGS. 19 and 20 to designate similar components.

In operation, switching of the diverter element to provide flow to the irrigation ditch via right outlet passage requires aspirated air inflow from both of air lines 321 and 351 to left control port 317. Consequently as long as plug 347 blocks opening 349 of air line 351 water from diverter element 307 cannot flow to the irrigation ditch. The bi-metallic strip 345 is adjusted so that plug 347 blocks opening 349 for temperatures at or below freezing; for higher temperatures the bi-metallic strip bends away from the opening 349 to permit aspirated air inflow through air line 351.

It is to be noted that the bi-metallic strip 345 can serve as a high temperature monitor rather than a freezing temperature by simply reversing the direction of motion of the strip so that the plug 347 moves toward opening 349 in response to increasing rather than decreasing temperature.

Another ambient parameter to be considered in terms of controlling the fluidic irrigation diverters is the wind in the vicinity of the irrigation ditch. It may, for example, be desirable to prevent irrigation in high winds because the water would be blown out of the normal irrigation channels. In FIG. 21 there is diagrammatically illustrated a wind override sensor unit 355 which circuit-wise is readily substituted for either the soil moisture sensor 325 or ambient temperature sensor 345 of FIGS. 19 and 20 respectively. Wind sensor 355 comprises a weather vane 357 symmetrically secured to one end of a horizontally disposed tube 359, said one end of the tube being open. The vane 357 is oriented in a vertical plane so that wind acts thereagainst tending to point the vane in the wind direction. Tube 359 includes a right angle bend so that its other end extends vertically downward into a rotary seal and bearing arrangement 361. This rotary seal and bearing arrangement is secured at the top of an air plenum which there-

fore is in fluid communication via tube 359 with ambient air at the open end of tube 359. An outlet port from plenum 365 communicates with an air line which in turn is connected to a control nozzle, for example control nozzle 317 in FIG. 20, of a fluidic diverter element.

Vane 357 keeps the open end of tube 359 pointed in the downwind direction since any wind acting against vane 357 tends to rotate tube 359 about the rotary bearing 361. A relatively high wind aspirates fluid from tube 359 via its open end and in turn creates a negative pressure in plenum 363 and plenum outlet opening 365. This negative pressure prevents aspiration by the diverter element of air from plenum 363 and therefore prevents switching of the diverter element to the irrigation ditch. In the absence of a high wind, aspiration of fluid from the plenum permits switching of fluid to the irrigation ditch.

Plenum 363 acts as a filter for high frequency wind transients and thereby ensures that only high steady winds will prevent irrigation. The logic associated with the circuit of FIG. 20 is the same when wind override 355 is employed in place of the temperature override 345.

FIG. 22 illustrates a modification of the wind override sensor of FIG. 21 wherein a flexible tube 359' replaces the rotatable tube 359 of FIG. 21. In addition the vane is provided with cross fins 357' so that two pairs of mutually perpendicular fins extend outwardly from the upper portion of tube 359'.

The arrangement of FIG. 22 responds to high winds causing a flexure or bending of tube 359' away from the wind. At wind velocities above a predetermined level a sufficient negative pressure is developed at the upper open end of tube 359' to inhibit switching of the fluidic diverter element connected to plenum outlet opening 365.

Any one or more of the ambient condition sensors discussed above may be employed in a single diverter control circuit. The AND logic employed can readily be extended to prevent diverter switching unless inflow from three or more sensors is present.

Utilizing the various sensing and detecting principles described hereinabove, it is possible to implement a number of different types of irrigation systems controlled by fluidic elements. For example, in some irrigation applications it is desirable to balance the flow into two or more channels or fluid holding structures so that the water level in each is maintained the same. Such a flow balancing system is illustrated schematically in FIG. 23 wherein the liquid levels in containers 367 and 369 are to be maintained equal in spite of the fact that the liquid in one container, for example container 369, may be utilized at a faster rate than the liquid in the container 367. Water from a reservoir 371 is applied under pressure to the power nozzle of a bistable fluidic master diverter 373, for example of the type illustrated in FIG. 1 herein. Right control port 375 of diverter 373 has a restricted opening and is utilized as a bias control port, and left control port 374 has a relatively large opening and is employed as a sensing control port. Left outlet passage 376 feeds the next diversion point in the chain of diverters whereas right outlet passage 377 feeds the flow balancing circuit which controls the levels in containers 367 and 369.

The flow balancing circuit includes a proportional fluidic diverter 380 for example of the type illustrated in FIG. 2 herein, which has its power nozzle connected to receive flow from right outlet passage 377 of master diverter 373. Diverter element 380 has left and right output passages 382 and 383 respectively which deliver fluid flowing therein to respective containers 369 and 367.

A pair of substantially identical inverted liquid level sensor cups 387 and 389 are disposed in the respective liquid containers 367 and 369. Inverter cups 387 and 389 are of the proportional level detection type such as described in relation to FIG. 12 hereinabove; however for illustration purposes sensor cup 387 is provided with a vertical row of small holes 388 rather than the vertical slots provided in the sensor cup of FIG. 12; likewise sensor cup 389 is provided with a vertical

row of small holes 390. Thus, the area through which air can pass into the cups gradually decreases as the level in the containers 369 and 367 rises.

The top of inverted sensor cup 387 is in fluid communication with the left control port 384 of diverter element 380 by means of a fluid passage 391. Similarly, the top of the inverted sensor cup 389 is in fluid communication with the right control port 385 of element 380 by means of fluid passage 393. Passages 391 and 393 are interconnected by means of a fluid passage having a pair of orifice type restrictors 395 and 397 disposed therein. Restrictors 395 and 397 have substantially identical flow characteristics. An additional fluid interconnection is provided between left control port 374 of master diverter element 373 and a junction between the two orifice restrictors 395 and 397.

Utilization of liquid from tanks 367 and 369 is accomplished through orifices 401 and 403 which for purposes of illustration are described as feeding respective adjustable valves 405 and 407. In order to illustrate the versatility of the arrangement in FIG. 23, the flow from orifice 403 in tank 369 is assumed to be substantially larger than the flow from orifice 401 in tank 367.

In operation, inverted sensor cups 387 and 389 permit aspiration of air to control ports 384 and 385 respectively at flow rates which are proportional to the liquid level in respective tanks 367 and 369. Consequently the outflow from proportional diverter element 380 is unbalanced to the extend that the usage flow from tank 369 exceeds the usage flow from tank 367. Aspiration of air into left control port 374 of master diverter 373 continues until the liquid level in both containers 367 and 369 covers the respective holes 388 and 390 in sensor cups 387 and 389. Thus master diverter 373 provides flow to analog diverter 383 whenever the level in either of tanks 367 and 369 is below a predetermined level; when the level in both tanks exceeds that predetermined level aspiration of air by left control port 374 of master diverter 373 is cut off and flow through element 373 proceeds to the next flow diversion point.

Master diverter 373 may, if desired, also be of the analog type, for example of the type illustrated in FIG. 2 herein, so that diverter element 373 diverts a total water flow in accordance with the average unfilled depth in both of containers 367 and 369. In such a case, only when both containers 367 and 369 are filled does the diverter 373 provide all of its flow through outlet passage 376; in all other instances a portion of the flow is provided by outlet passage 377 to analog diverter 380.

The logic approach in the arrangement of FIG. 23 may be extended for a system distributing flow among a larger number of containers by merely adding additional "levels" or "orders" of diverters. A system of this type is schematically illustrated in FIG. 24 where flow balancing is required to maintain equal liquid levels in eight liquid containers 411 through 418. The principles of operation involved in the arrangement of FIG. 24 are the same as those involved in the arrangement of FIG. 23; consequently, further detailed description would be superfluous. What is important however is the fact that the first "order" or "level" diverter 421 proportions flow received from the master diverter among the two second "order" or "level" diverters 422 and 423, the proportioning being effected as a function of the total inflow requirements of containers 411 through 414 as compared to the total inflow requirements for containers 415 through 418. Similarly, each second "level" diverter element 422 and 423 proportions liquid received thereby between a respective pair of third "level" diverter elements. The third "level" elements feed directly into the containers.

To further expand the system of FIG. 24, when the number of containers to be filled equals 2^n , the number of levels of diverter elements required is n and the number of diverters required is 2^{n-1} . For efficient filling, the diverters in an upper level should be capable of technology twice the flow as those in the next lower level.

In certain types of irrigation systems in which control of a downstream liquid level is to be achieved, it is desirable to adjust the flow from the diverter in accordance with a predetermined time pattern, or schedule, in order to compensate for time lags required by the issued water to perform some function or establish its final level. A typical example in the control of water flow to a long irrigation ditch is the response to new flow demand at the downstream end. If the upstream flow is increased upon each incremental flow demand, a considerable time elapses before the flow at the downstream end increases to the new desired level. This time delay is caused by several factors: the time required for the water to flow downstream to the usage control structure; the time required to fill the irrigation ditch to a higher level so that it will transport the increase flow; and, if the usage structure is a simple overflow device, such as a weir, the time required to raise the water level immediately upstream so that the usage structure can pass the required incremental flow. These delays can be reduced by initially providing a higher flow rate into the irrigation ditch than that "requested" by a downstream flow sensor, and then reducing the flow rate to that responding to the sensor demand. In control system technical this type of function is termed a "lead" or anticipatory function. A classic method of generating a lead function or lead effect is to perform the desired control function with a closed loop controller and introduce a delay or lag in the operation in the feedback portion of the loop. This in effect allows the controller output to initially overshoot then recede to the desired level as the feedback signal gradually builds up to its proper level. A number of the irrigation flow control concepts described hereinabove are of the desired closed loop variety. Several of these can be employed to generate the necessary lead effect through a lag in the feedback action. An arrangement for providing this is illustrated in FIG. 14 and in slightly modified form in FIG. 25. In FIG. 25, water in a container or tank 431 is selectively distributed by means of diverter element 433 to either irrigation ditch 435 or to a subsequent flow diversion point. Diverter element 433, by way of example, may be of the type illustrated in FIG. 1 and comprises a left control port 434 utilized as a sensing port, a right control port 436 utilized as a bias port, and left and right outlet passages 437 and 438 respectively. Right outlet passage 438 issues water directly into the irrigation ditch 435. Disposed in irrigation ditch 435 is a standpipe 439 having an orifice 441 defined through one of its walls at a level below some sensor reference level A—A¹. Ditch 435 and standpipe 439 are shown in section in FIG. 25; to avoid confusion however it should be pointed out that the flow in ditch 435 has free access around the standpipe so that the standpipe does not in any way isolate flow between its up and downstream sides. An inverted level sensor cup 443 is mounted in standpipe 439 with its rim at the reference level A—A¹. The interior of sensor cup 433 communicates, by means of fluid passage 445, with the left control port 434 of diverter 433.

In operation, as ditch 435 is filled, standpipe 439, which extends above the maximum permissible water level in ditch 435, is filled by means of inflow through orifice 441. Inflow through this orifice is relatively slow due to small orifice size and therefore the water level in standpipe 439 rises much more slowly than the water level in ditch 435. Consequently, the upstream end of ditch 435 experiences a water level rise substantially above reference level A—A¹ before the water level in standpipe 439 reaches that level. Of course, once the water level in the standpipe reaches level A—A¹ diverter 433 is switched and flow to ditch 435 terminates.

The delay time for switching diverter element 433 may be extended by increasing the standpipe volume and/or by decreasing the area of orifice 441. In actual practice, the desired delay time is established as a function of the length, capacity, and ability to handle transient flows in irrigation ditch 435.

The arrangement of FIG. 25 may of course be operated in an analog or proportional mode by replacing diverter 433 with

a diverter of the type illustrated in FIG. 2 and by replacing the solid-wall sensor cup 443 by a perforated sensor cup of the type illustrated in either of FIGS. 12 or 23.

An alternative arrangement for providing a lead function in a liquid level control is illustrated schematically in FIG. 26. In this embodiment the diverter 433 alternatively feeds the irrigation ditch 435 or a downstream diversion point as is the case with the arrangement in FIG. 25; however standpipe 439 is eliminated in FIG. 26 and the sensor cup 433 is supported directly in the ditch with its rim at the reference level A—A¹. The lead function in this embodiment is provided by means of an air plenum 446 which communicates with air line 445 interconnecting the level sensor cup 443 and left control port 434 of diverter element 433. When the rim of sensor cup 443 is unblocked, air is aspirated through the cup and air line 445 to control port 434 causing diverter 433 to feed water to ditch 435 via outlet passage 438. When the water in ditch 435 rises to level A—A¹ and blocks the mouth of sensor cup 443, the left control port 434 of diverter 433 continues to aspirate air but such aspiration operates on the air in plenum 446 rather than the air in sensor cup 443. Flow to ditch 435 thus continues until such time as the air in plenum 446 is completely aspirated. The extent of the delay between blockage of cup 443 and switching of element 433 is proportional to the plenum volume and inversely proportional to the cross sectional area of control port 434.

It should be noted that other time shaping functions can be implemented with combinations of orifices, plenums, and standpipes, etc. If more complex flow demand functions are desired, fluidic elements, operating either on air or water can be utilized to implement complete computers, operating in digital and/or analog modes. Such computers could for example establish an optimum flow program for an upstream flow control structure taking into account such factors as the distributor usage demands, local rain fall, seepage losses into the canal banks and bed, evaporation losses as a function of temperature, etc.

The various elements and circuits described in detail hereinabove are intended for primary utility in fluidically controlled irrigation systems, although it will be understood that broader utility than irrigation is possible in a number of water management and control systems. The irrigation control systems to be described hereinbelow employ the various techniques and circuits described above to achieve desired control and distribution of irrigation water. Referring specifically to FIG. 27 three is illustrated in schematic form an automatic irrigation system for use in a sloping terrain environment. A reservoir 451 is located at the high point of the terrain. A first fluidic diverter element 453, for example of the type illustrated in FIG. 1 herein, has its power nozzle adapted to receive water under pressure from reservoir 451 and distribute the water via respective outlet passages to either a lateral distribution ditch 454 or to the power nozzle of a downstream diverter 455 located somewhat downslope from diverter 453. Water received by lateral distribution ditch 454 is in turn distributed to a plurality of furrows 457 by means of which the surrounding soil is irrigated. A sensor element, for example of the type illustrated in FIG. 13 is employed to detect when the liquid in furrows 457 achieve a predetermined level, at which time diverter element 453 is switched and flow therefrom proceeds to diverter element 455.

Diverter element 455 distributes water supplied thereto to either of lateral distribution ditch 459 or the power nozzle of downstream diverter element 460. Lateral distribution ditch 459 feeds respective furrows 457 and flow to ditch 459 is maintained until the water in these furrows reaches a predetermined level. Upon achieving the predetermined level in furrows 457, water from element 455 is switched to element 460 which first fills lateral distribution ditch 461 and furrows 457 associated therewith and then fills a lateral distribution ditch 462 and furrows 457 associated therewith. Any number of downslope sections may be filled in accordance with this logic arrangement, each level requiring a respective diverter.

The "top-down" sequence of operation for the system in FIG. 27 can be reversed to provide a "bottom-up" sequence whereby the switching of diverter element 453 would be controlled by the liquid level in the furrows associated with distribution ditch 459; the switching of diverter element 455 would be controlled by the water level in the furrows associated with distribution ditch 462; and the switching of diverter element 460 would be as illustrated in FIG. 27.

If it is desired to control the sequence of diverters on a time basis instead of a "filled furrow" basis, the sensor can be located in a tank into which water is allowed to seep into the soil from the diverter outlet through a calibrated orifice or capillary. The timing interval is thus controlled by the tank volume, seepage flow cross sectional area, and depth setting of the sensor in the tank. The operation of such a scheme is quite analogous to that illustrated in FIG. 18 wherein the metering cup 301 would represent the tank receiving the seepage flow. Another approach for controlling the sequencing of diverters on a time basis rather than a "fill" basis is illustrated by means of the sensor arrangement in FIGS. 14, 25 and 26. The time sequence approach can be implemented with shorter communication lines between the diverter and sensor although the approach does require the addition of a tank or suitable time delay means.

Another system for cyclically filling irrigation ditches is illustrated in FIG. 28 in which eight irrigation ditches 471 through 478 respectively are sequentially filled in the order named by means of a circuit comprising seven fluidic diverters 481 through 487, for example of the type illustrated in FIG. 1. The sensor elements employed, by way of example, may be of the type illustrated in FIGS. 13 or 14 and provide an indication as to when the liquid in each respective ditch achieves a predetermined level at which time flow to that ditch is to be terminated. The cycle associated with the system of FIG. 28 is self-repetitive.

Water enters the power nozzle of element 481 from the supply ditch, which by way of example should be at least nine to twelve inches higher than the irrigation ditches. At the start of the cycle, the water exits through the right outlet passage of element 481 and flows to element 482. Element 482 is biased to its right outlet passage so that the flow proceeds to element 484 which is likewise biased and flow is issued into irrigation ditch 471. When the water in ditch 471 rises to block off air entrainment in its sensor cup, element 484 switches its output flow to its left output leg and begins filling ditch 472. When ditch 472 achieves a water level equal to that of the mouth of its sensor cup, element 482 switches and the sequence continues until eventually ditch 478 is full and the entire cycle is repeated.

The bistable fluidic diverter illustrated in FIG. 1 may serve the purpose of a shut off valve in the irrigation system when employed as schematically illustrated in FIG. 29. In this system a portion of the water flow in a main supply ditch is directed to the supply port or power nozzle of bistable diverter element 490. Similarly, at various downstream locations portions of the flow in the main supply ditch are directed to respective power nozzles of bistable fluidic diverters, for example, diverter 491. The right outlet passages of each of diverter elements 490 and 491 communicate with respective irrigation ditches and the left outlet passages of these diverter elements direct flow back into the main supply ditch. It is clear that by simply blocking or unblocking the appropriate control ports at diverter elements 490, 491, such as with appropriate liquid level detectors of the type described herein, water can be directed either to the irrigation ditch associated with that element or back into the main ditch flow.

A weir 492 is disposed in the output line between the right outlet passage of element 490 and its irrigation ditch. This weir is set at about the same level as the water level of the main supply ditch to prevent water from reaching the irrigation ditch unless element 490 is in fact switched to provide such flow. Since the static pressure or head usually available in the irrigation output leg (right output leg) is relatively small, a

relatively wide weir 492 would be employed to obtain desired flow. A similar weir 493 is employed between the right outlet passage of element 491 and its associated irrigation ditch.

In cases where a relatively low flow velocity exists in the main ditch, weirs 494 may be provided to produce a small head change along the supply ditch between the power nozzle and left outlet passage of each fluidic element.

The blocking and unblocking of elements 490 and 491 may be accomplished by a liquid level sensing or other types of self-cycling, programmed or remote control arrangements.

An automated fluidically controlled siphon irrigation system is illustrated diagrammatically in FIGS. 30 and 31. Referring first to FIG. 30, each growing area is serviced by a large fluidically controlled siphon of the type described above in relation to FIG. 9. Water from a main supply ditch 495 enters a lateral ditch 497 by means of a controlled gate 496, for example of the roller curtain type described herein. When water is supplied to lateral ditch 497, siphon 498 associated with the growing area number 1 discharges into a distribution ditch which feeds the crop furrows in growing area No. 1. When level sensor No. 1 associated with fluidically controlled siphon 498 is actuated, flow through the siphon 498 terminates and the next fluidically control siphon 499, associated with growing area No. 2 and which is interlocked with the operation of siphon 498, begins to flow until it is turned off by the level sensor in growing area No. 2. Fluidically controlled siphon 501, associated with growing area No. 3, begins to flow at this time, and the cycle thus continues until all growing areas along lateral ditch 497 have been irrigated.

The logic sequence associated with the system of FIG. 30 is illustrated in greater detail in FIG. 31. In operation, a fluidic diverter associated with fluidically controlled siphon 498 flows to its left outlet channel, designated as the ON channel in FIG. 31, as soon as the water level in lateral ditch 497 covers the upstream side of siphon 498. This is because more air can be aspirated into the right control port of the diverter from level sensor No. 1 than is aspirated into the restricted left control port. Siphon 498 starts and fills the distribution ditch associated with growing area No. 1 and terminates when level sensor No. 1 indicates the desired liquid level has been achieved. Liquid level sensor 01, in addition to supplying air to the right control nozzle of the diverter associated with siphon 498, also supplies most of the air to the least or bias control nozzle of the fluidic diverter associated with siphon 499. The additional air is supplied through the small restricting orifice R₁. Thus, prior to liquid in growing area No. 1 achieving the desired level, the combined air flows from sensor No. 1 and R₁ acts to maintain the diverter associated with siphon 499 in its off condition. When air flow through level sensor No. 1 terminates therefore, in addition to turning off the diverter associated with siphon 498, level sensor 01 also turns on the diverter associated with siphon 499, since the air flow through restricting orifice R₂ is greater than through R₁. At this time siphon 499 begins to flow into its associated distribution ditch filling growing area No. 2. When level sensor No. 2 detects the reference level in growing area No. 2, aspirated air flow through R₂ to the right control nozzle of the diverter associated with siphon 499 terminates. In addition, most of aspirated air flow to the left or bias control nozzle of the diverter associated with siphon 501 terminates. Consequently siphon 499 turns off as a result of the aspirated air flow through R₁, and siphon 501 turns on and irrigation of growing area No. 3 commences.

The siphon flow period for any and all of the growing areas can be controlled using either the fill or time interval logic arrangements described hereinabove. The siphon units 498, 499 and 501 may either be portable, such as diagrammatically illustrated in FIG. 30, or may be permanently installed between lateral ditch 497 and the various distribution ditches in the growing areas.

In many low slope irrigation systems, mechanical gates, of either the surface overflow or submerged types, are employed to transfer irrigation water from lateral ditches to the growing

areas. These systems can be automated using the same basic fluidic logic described above in relation to FIGS. 30 and 31. Also, depending upon specific structural configuration, variations of the leaky bucket actuator and roller curtain gate described in relation to FIGS. 3 and 4 are readily adaptable to these systems.

There are many irrigation systems in which water is pumped to the growing areas rather than directed through the open ditches under gravity head. This water is distributed to the crops through a variety of sprinkler arrangements, etc. The prior art method of controlling flow in such systems is by standard manual gate valves. In the automation of such systems by conventional electrical, mechanical or hydraulic valves, an auxiliary energy supply of considerable capacity must be installed and the expense for such, in addition to the expense for the valves, sensors and communication lines, must be incurred. In comparison, fluidic implementation makes use of the available energy in the water flow for actual control, thereby eliminating the auxiliary energy supply system.

While I have described and illustrated specific embodiments of my invention, it will be clear that variations of the details of construction which are specifically illustrated and described may be resorted to without departing from the true spirit and scope of the invention as defined in the appended claims.

I claim

1. A fluidic diverter element adapted for use in a specified ambient fluid environment to selectively distribute a working fluid between at least two flow paths, said working fluid having a greater density than said ambient fluid, said element comprising:

an interaction region;

a power nozzle having an inlet opening and responsive to application of pressurized working fluid to said inlet opening for issuing a power stream of said working fluid into said interaction region;

at least one outlet passage having an ingress opening disposed for receiving said power stream at the downstream end of said interaction region, said outlet passage having an open downstream end;

weir means for preventing outflow of said working fluid from the open downstream end of said outlet passage unless the fluid pressure at the ingress opening of said outlet passage exceeds a predetermined minimum pressure; and control means for selectively deflecting said power stream relative to said outlet passage such that for at least one position of said power stream the fluid pressure at the ingress opening of said at least one outlet passage exceeds said predetermined minimum pressure.

2. The fluidic diverter element according to claim 1 wherein said working fluid is a liquid, wherein said interaction region has at least one sidewall and wherein said control means comprises: a vortex chamber projecting outwardly from said interaction region through an upstream section of said sidewall, said vortex chamber being disposed to receive a small portion of said power stream and create vortical flow thereof in said vortex chamber, and a control port communicating between ambient pressure and said vortex chamber axially of said vortical flow, whereby said vortical flow creates a suction at said control port to induce inflow of ambient fluid into said interaction region.

3. A system employing a liquid working fluid and the fluidic diverter element of claim 2 for maintaining the liquid level in one of said two flow paths at a predetermined level, said system further comprising a sensor cup, means for supporting said sensor cup with its open end facing downward and the rim of said open end disposed at said predetermined level in said one of said flow paths, and a fluid passage interconnecting the interior of said cup and said control port such that ambient fluid is supplied from said sensor cup to said control port unless the open end of said sensor cup is blocked by the liquid in said one of said flow paths.

4. A system employing the fluidic diverter element of claim 2 and a liquid as a working fluid, said system further comprising:

a metering cup, open at its top, and having an adjustable drain orifice at its bottom; means for conducting a known small proportion of said liquid flowing through said one outlet passage into said metering cup;

5 a sensor tube having one end extending a predetermined depth into said metering cup and a second end connected to said control port of said diverter element, whereby upon the liquid in said metering cup rising to the level of said one end of said sensor tube, inflow of ambient fluid to said control port is terminated and liquid flow through said one outlet passage ceases.

10 5. The fluidic diverter element according to claim 2 wherein said one sidewall is positioned to permit boundary layer lockon thereto by said power stream, and wherein said power stream is directed toward said one outlet passage when said power stream is locked onto said one sidewall, said predetermined minimum pressure at said one outlet passage being exceeded when said power stream is locked onto said one sidewall.

15 6. The fluidic diverter element according to claim 5 wherein the size of said control port permits sufficient ambient fluid inflow to said interaction region to provide deflection of said power stream relative to said one outlet passage as a proportional function of the ambient fluid inflow rate.

20 7. The fluidic diverter element according to claim 5 wherein said diverter element comprises top and bottom joined plates, said weir means being formed by a surface in said bottom plate which slopes upwardly toward said top plate in a downstream direction at the downstream end of said outlet passage.

25 8. The fluidic diverter element according to claim 1 further comprising:

30 a second outlet passage having an ingress opening disposed for receiving said power stream at the downstream end of said interaction region, said one and said second outlet passages being separated by a flow splitter, said second outlet passage having an open downstream end; further weir means for preventing outflow of said working fluid from the open downstream end of second outlet passage unless the fluid pressure at the ingress opening of 35 said second outlet passage exceeds a specified minimum pressure; and

35 first and second sidewalls for said interaction region, said sidewalls being positioned such that said power stream can lock onto either sidewall, and wherein said power stream is directed toward said one outlet passage and exceeds said predetermined minimum pressure thereat when locked onto said first sidewall and is directed toward said second outlet passage and exceeds said predetermined minimum pressure thereat when locked onto said second sidewall; and

40 wherein said control means comprises first and second vortex chambers projecting outwardly from said interaction region through said first and second sidewalls respectively, each of said vortex chambers being disposed to receive respective small portions of power stream fluid tangentially of the vortex chamber to create vertical flow therein, each vortex chamber having a respective one of first and second control ports communicating between ambient fluid and said vortex chamber axially of said vertical flow, whereby said vertical flow creates a suction at said control port to induce inflow of ambient fluid into said interaction region

45 9. The fluidic diverter element according to claim 8 wherein said diverter element is constructed from top and bottom joined plates, said weir means and said further weir means being formed by respective surfaces in said bottom plate which slope upwardly toward said top plate in a downstream direction at the downstream end of each of said outlet passages.

50 10. A system employing the fluidic diverter element according to claim 8 wherein the working fluid is a liquid, said system being employed for maintaining the liquid level in one of said two flow paths at a predetermined level, said system additionally comprising:

a sensor cup, means for supporting said sensor cup with its open end facing downward and the rim of said open end disposed at said predetermined level in said one of said two flow paths; and

5 a fluid passage interconnecting the interior of said cup with the one of said control ports communicating with said first vortex chamber such that ambient fluid is supplied from said sensor cup to said one control port unless the open end of said sensor cup is blocked by the liquid level in said one flow path.

10 11. An irrigation system employing the combination according to claim 10 wherein said ambient fluid is ambient air and further comprising override means operative in conjunction with said control means for limiting inflow of ambient air to said one of said control ports whenever an ambient environment parameter has a value lying outside a predetermined range of values, said override means including:

15 a flow tube having one end in fluid communication with said fluid passage and an open second end; and sensing means for selectively blocking and unblocking said second end of said flow tube in accordance with whether or not said ambient environment parameter has a value within said predetermined range of values;

20 25 wherein the relative sizes of said control ports are such that said power stream attaches to said first sidewall only when the rim of said sensor cup is not blocked by liquid in said one flow path and the second end of said flow tube is not blocked by said sensing means.

30 35 12. The system according to claim 11 wherein said ambient environment parameter is ambient temperature.

40 13. The system according to claim 11 wherein said ambient environment parameter is ambient temperature and wherein said sensing means comprises:

45 a bi-metal strip fixedly secured at one end and responsive to temperature increases above a predetermined nominal temperature for pivoting about said one end in a first direction and responsive to temperature decreases below said predetermined nominal temperature for pivoting about said one end in a second and opposite direction; and

50 means secured to said bi-metal strip for blocking said second end of said sensor tube whenever said bi-metal strip pivots a predetermined angle in one of said first and second directions.

55 14. The system according to claim 11 wherein said ambient environment parameter is wind velocity, and wherein said sensing means comprises a movably mounted tube having one end in flow communication with the second end of said sensor tube and its other end open to ambient air, a plurality of vane members secured to said movably mounted tube proximate said other end such that wind forces acting on said vane members tend to move said movably mounted tube to a position in

60 55 which said other end faces downstream of the wind and air is aspirated therefrom by the wind, whereby for wind velocities below a specified level sufficient air inflow is provided to said other end of said movably mounted tube to cause said power stream to attach to said first sidewall if the level of liquid in said one flow path is below said predetermined level.

65 15. The fluidic diverter element according to claim 8 wherein the sizes of said control ports permit sufficiently large inflow rates of ambient fluid into said interaction region to provide deflection of said power stream relative to said outlet passages as a proportional function of the ambient fluid inflow rate.

70 16. The system according to claim 15 wherein said working fluid is a liquid and said ambient fluid is air and wherein said system is employed to balance liquid inflow between two liquid containers in accordance with the difference between outflows from said two containers, said system further comprising:

75 first variable flow restriction means disposed in a first of said two liquid containers and connected in flow communication with said first control port for restricting the flow

of ambient air to said first control port as a proportional function of the liquid level in said first container; and second variable flow restriction means disposed in the second of said two containers and connected in flow communication with said second control port for restricting the flow of ambient air to said second control port as a proportional function of the liquid level in said second container; and means for directing liquid flowing through said first outlet passage into said first container and liquid flowing through said second outlet passage into said second container; whereby the difference between liquid levels in said two containers determines the difference between liquid inflows to said two containers.

17. The system according to claim 16 wherein said variable flow restriction means each comprise a cup having an open end disposed proximate the bottom of a respective container, a closed end extending upwardly to some higher level in the container, a fluid passage communicating between the closed end of said cup and a respective control port, and a plurality of openings in the side of the cup arranged so that increasingly greater portions of the total area of said openings are blocked by a rising liquid level in said container.

18. The system according to claim 16 further comprising a bistable fluidic diverter element having two outlet passages, one of which is connected directly to the power nozzle the proportional fluidic diverter element, and means for selectively switching pressurized liquid from one to the other of the outlet passages of said bistable fluidic diverter element.

19. The system according to claim 16 further comprising a second substantially identical proportional diverter element for distributing liquid inflow between two further liquid containers in accordance with the difference between liquid levels in said two further containers as sensed by two further variable flow restriction means, said system further comprising a bistable fluidic element having first and second outlet passages and means for selectively switching a liquid power stream from one to the other of said last-mentioned outlet passages, and means for connecting said last-mentioned outlet passages to the power nozzles of respective ones of said proportional diverter elements.

20. A fluidic diverter element comprising an interaction region, a power nozzle responsive to application of pressurized fluid thereto for issuing a power stream of fluid into said interaction region, at least one outlet passage disposed in receiving relation to said power stream at the downstream end of said interaction region, at least one sidewall of said interaction region disposed to permit boundary layer lockon thereto by said power stream, at least one control port defined through said sidewall and communicating between ambient fluid and said interaction region, said one control port being disposed such that ambient fluid is entrained therethrough by said power stream, wherein the size of said control port permits sufficient ambient inflow to said interaction region to deflect said power stream as a proportional function of the ambient fluid inflow rate and further including a vortex chamber projecting outwardly from said interaction region through said sidewall and disposed to receive a small portion of said power stream tangentially of said vortex chamber to create vortical flow in said vortex chamber, and wherein said control port communicates between an ambient fluid environment and said vortex chamber axially of said vortical flow, whereby said vortical flow creates a suction for inducing inflow of ambient fluid into said interaction region.

21. A fluidic diverter element comprising an interaction region, a power nozzle responsive to application of pressurized fluid thereto for issuing a power stream of fluid into said interaction region, at least one outlet passage disposed in receiving relation to said power stream at the downstream end of said interaction region, at least one sidewall of said interaction region disposed to permit boundary layer lockon thereto by said power stream, at least one control port defined through

said sidewall and communicating between ambient fluid and said interaction region, said one control port being disposed such that ambient fluid is entrained therethrough by said power stream, wherein the size of said control port permits sufficient ambient inflow to said interaction region to deflect said power stream as a proportional function of the ambient fluid inflow rate, and wherein said diverter is employed to monitor liquid level in a container and further comprises:

a sensor cup having an open end, a closed end, at least one sidewall and a vertically extending slot defined through said sidewall, said sensor cup being disposed in said container with said open end facing downward; and a tube for providing fluid interconnection between the interior of said sensor cup at the closed end thereof and said at least one control port of said fluidic diverter element; whereby inflow of ambient fluid to said at least one control port via said vertically extending slot is restricted as a function of the level of liquid in said container.

22. A fluidic diverter element capable of operating in either a proportional mode or bistable mode, said diverter element comprising:

an interaction region;
a power nozzle responsive to application of pressurized fluid thereto for issuing a power stream of fluid into said interaction region;

first and second outlet passages disposed for receiving respective portions of said power stream at the downstream end of said interaction region as a function of deflection of said power stream;

first and second control ports communicating between an ambient fluid environment exterior of said diverter element and said interaction region at respective opposite sides of said power stream and adapted to permit aspiration of ambient fluid by said power stream into said interaction region;

a pair of sidewalls defining opposite sides of said interaction region and disposed such that when air inflow from said control ports is at less than a predetermined flow rate said power stream is stable only when attached to either of said sidewalls;

wherein said control ports are sufficiently large to prevent attachment of said power stream to said sidewalls unless said control ports are completely blocked to ambient fluid flow; and further comprising:

first and second insert means adapted to fit over said first and second control ports respectively for restricting ambient fluid inflow through said control ports sufficiently to render said power stream stable only when attached to either of said sidewalls; and

first and second projections extending outwardly from respective sidewalls of said interaction region immediately downstream of said power nozzle and configured to scoop off respective portions of said power stream to create vortical fluid flow therefrom in said projections, wherein said first and second control ports communicate with said interaction region through respective ones of said first and second projections in axial relation to the vortical flow in said projections.

23. A fluidic diverter element capable of operating in either a proportional mode or bistable mode, said diverter element comprising:

an interaction region;
a power nozzle responsive to application of pressurized fluid thereto for issuing a power stream of fluid into said interaction region;

first and second outlet passages disposed for receiving respective portions of said power stream at the downstream end of said interaction region as a function of deflection of said power stream;

first and second control ports communicating between an ambient fluid environment exterior of said diverter element and said interaction region at respective opposite sides of said power stream and adapted to permit aspiration

tion of ambient fluid by said power stream into said interaction region;

a pair of sidewalls defining opposite sides of said interaction region and disposed such that when air inflow from said control ports is at less than a predetermined flow rate said power stream is stable only when attached to either of said sidewalls;

wherein said control ports are sufficiently large to prevent attachment of said power stream to said sidewalls unless said control ports are completely blocked to ambient fluid flow; and

a system employing said fluidic diverter element and utilizing a liquid as a working fluid, said system comprising:

a metering cup, open at its top, and having an adjustable drain orifice at its bottom;

means for conducting a known small proportion of liquid flowing through said one of said outlet passages into said metering cup;

sensor tube having one end extending a predetermined depth into said metering cup and a second end connected to one of said control ports of said diverter element;

whereby upon the liquid in said metering cup rising to the level of said one end of said sensor tube, inflow of ambient fluid to said one of said control ports is terminated and liquid flow through said one of said outlet passages ceases.

24. A fluidic diverter element capable of operating in either a proportional mode or bistable mode, said diverter element comprising:

an interaction region;

a power nozzle responsive to application of pressurized fluid thereto for issuing a power stream of fluid into said interaction region;

first and second outlet passages disposed for receiving respective portions of said power stream at the downstream end of said interaction region as a function of deflection of said power stream;

first and second control ports communicating between an ambient fluid environment exterior of said diverter element and said interaction region at respective opposite sides of said power stream and adapted to permit aspiration of ambient fluid by said power stream into said interaction region;

a pair of sidewalls defining opposite sides of said interaction region and disposed such that when air inflow from said control ports is at less than a predetermined flow rate said power stream is stable only when attached to either of said sidewalls;

wherein said control ports are sufficiently large to prevent attachment of said power stream to said sidewalls unless said control ports are completely blocked to ambient fluid flow; and

a system employing a liquid working fluid and said fluidic diverter element for maintaining the liquid level in a flow path at a predetermined level, said system comprising:

means conducting liquid from one of said outlet passages to said flow path; a sensor cup; means for supporting said sensor cup with its open end facing downward and the rim of said open end disposed at said predetermined level in said flow path; and a fluid passage interconnecting the interior of said cup and one of said control ports such that ambient fluid is supplied from said sensor cup to one of said control ports unless the open end of said sensor cup is blocked by the liquid in said flow path.

25. An irrigation system employing the combination according to claim 24 wherein said ambient fluid is ambient air and further comprising override means operative for limiting inflow of ambient air to said one of said control ports whenever an ambient environment parameter has a value lying outside a predetermined range of values, said override means including:

a flow tube having one end in fluid communication with said fluid passage and an open second end; and

sensing means for selectively blocking and unblocking said second end of said flow tube in accordance with whether or not said ambient environment parameter has a value within said predetermined range of values;

wherein the relative sizes of said control ports are such that said power stream attaches to said first sidewall only when the rim of said sensor cup is not blocked by liquid in said one flow path and the second end of said flow tube is not blocked by said sensing means.

26. The system according to claim 25 wherein said ambient environment parameter is soil moisture content and wherein said sensing means comprises:

a container at least partially buried in the soil having a funnel-shaped ingress opening at its top which extends above the soil for receiving rainfall, a drain passage at its bottom communicating between the container interior and the soil, and a sensor opening;

porous material disposed in said container and having water-absorbing characteristics approximating those of the surrounding soil, said porous material surrounding said sensor opening so that ambient air flow from said ingress opening to said sensor opening must pass through said porous material; and

means for preventing said porous material from lodging in said sensor opening;

wherein the density of said porous material in said container is such that when said porous material is saturated with water, substantially no air flow can occur between said ingress and sensor openings, and when the amount of water absorbed by said porous material is at or less than some specified amount there is sufficient air flow from said ingress opening to said sensor opening to cause said power stream to attach to said first sidewall if the liquid level in said one flow path is below said predetermined level.

27. The system according to claim 26 wherein said ambient environment parameter is ambient temperature.

28. The system according to claim 26 wherein said ambient environment parameter is ambient temperature and wherein said sensing means comprises:

a bi-metal strip fixedly secured at one end and responsive to temperature increases above a predetermined nominal temperature for pivoting about said one end in a first direction and responsive to temperature decreases below said predetermined nominal temperature for pivoting about said one end in a second and opposite direction; and

means secured to said bi-metal strip for blocking said second end of said sensor tube whenever said bi-metal strip pivots a predetermined angle in one of said first and second directions.

29. The system according to claim 26 wherein said ambient environment parameter is wind velocity, and wherein said sensing means comprises a movably mounted tube having one end in flow communication with the second end of said sensor tube and its other end open to ambient air, a plurality of vane members secured to said movably mounted tube proximate said other end such that wind forces acting on said vane members tend to move said movably mounted tube to a position in which said other end faces downstream of the wind and air is aspirated therefrom by the wind, whereby for wind velocities below a specified level sufficient air inflow is provided to said other end of said movably mounted tube to cause said power stream to attach to said first sidewall if the level of liquid in said one flow path is below said predetermined level.

30. A fluidic diverter element capable of operating in either a proportional mode or bistable mode, said diverter element comprising:

an interaction region;

a power nozzle responsive to application of pressurized fluid thereto for issuing a power stream of fluid into said interaction region;

first and second outlet passages disposed for receiving respective portions of said power stream at the

downstream end of said interaction region as a function of deflection of said power stream;

first and second control ports communicating between an ambient fluid environment exterior of said diverter element and said interaction region at respective opposite sides of said power stream and adapted to permit aspiration of ambient fluid by said power stream into said interaction region;

a pair of sidewalls defining opposite sides of said interaction region and disposed such that when air inflow from said control ports is at less than a predetermined flow rate said power stream is stable only when attached to either of said sidewalls;

wherein said control ports are sufficiently large to prevent attachment of said power stream to said sidewalls unless said control ports are completely blocked to ambient fluid flow; and

wherein said fluid is a liquid and said ambient fluid is air and wherein said diverter element is employed to balance liquid inflow between two liquid containers in accordance with the difference between outflows from said two containers, said system further comprising:

first variable flow restriction means disposed in a first of said two liquid containers and connected in flow communication with said first control port for restricting the flow of ambient air to said first control port as a proportional function of the liquid level in said first container; and

second variable flow restriction means disposed in the second of said two containers and connected in flow communication with said second control port for restricting the flow of ambient air to said second control port as a proportional function of the liquid level in said second container; and

means for directing liquid flowing through said first outlet passage into said first container and liquid flowing through said second outlet passage into said second container;

whereby the difference between liquid levels in said two containers determines the difference between liquid inflows to said two containers;

a second substantially identical proportional diverter element for distributing liquid inflow between two further liquid containers in accordance with the difference between liquid levels in said two further containers as sensed by two further variable flow restriction means;

a bistable fluidic element having first and second outlet passages and means for selectively switching a liquid power stream from one to the other of said last-mentioned outlet passages;

and means for connecting said last-mentioned outlet passages to the power nozzles of respective ones of said proportional diverter elements.

31. A fluidic diverter element capable of operating in either a proportional mode or bistable mode, said diverter element comprising:

an interaction region;

a power nozzle responsive to application of pressurized fluid thereto for issuing a power stream of fluid into said interaction region;

first and second outlet passages disposed for receiving respective portions of said power stream at the

downstream end of said interaction region as a function of deflection of said power stream;

first and second control ports communicating between an ambient fluid environment exterior of said diverter element and said interaction region at respective opposite sides of said power stream and adapted to permit aspiration of ambient fluid by said power stream into said interaction region;

a pair of sidewalls defining opposite sides of said interaction region and disposed such that when air inflow from said control ports is at less than a predetermined flow rate said power stream is stable only when attached to either of said sidewalls;

wherein said control ports are sufficiently large to prevent attachment of said power stream to said sidewalls unless said control ports are completely blocked to ambient fluid flow; and

a system employing said fluidic diverter element in a bistable operating mode wherein said working fluid is a liquid, said second outlet passage being arranged to issue liquid flowing therethrough into a flow channel, said system further comprising sensing means located proximate the upstream end of said flow channel for simulating liquid level sensing at the downstream end of said flow channel and terminating liquid flow through said second outlet passage whenever the liquid level sensed by said sensing means reaches a predetermined level.

32. The system according to claim 31 wherein said sensing means comprises:

a standpipe located in said flow channel proximate said upstream end so as not to prevent downstream flow through said channel, said standpipe having an aperture extending therethrough at a level below said predetermined level to permit leakage of liquid from said channel into said standpipe;

a sensor cup having an open end and a closed end and supported in said standpipe with said open end extending downward at said predetermined level; and

fluid passage means communicating between the closed end of said sensor cup and the second control port of said diverter element;

wherein the size of said aperture is chosen such that the rate of liquid level rise at the downstream end of said channel is simulated by the liquid level rise in said standpipe.

33. The system according to claim 31 wherein said sensing means comprises:

a sensor cup having an open end and a closed end and supported proximate the upstream end of said channel with said open end facing down at a specified level;

a fluid passage line communicating between said closed end and said second control port; and

an enclosure of predetermined volume communicating with said fluid passage line;

whereby ambient air is aspirated from said enclosure after the liquid level proximate the upstream end of said channel reaches said specified level to cover the open end of said sensor cup, the volume of said enclosure being selected such that said enclosure is substantially evacuated at a time corresponding to that when the liquid at the downstream end of said channel reaches said predetermined level.
